(57) **ABSTRACT**

Gaming systems and methods that include one or more symbols that trigger multiple symbol evaluations for a play of a game. Each of the trigger symbols can cause the gaming system and method to provide multiple independent symbol evaluations during a play of the game for the same set of randomly generated and displayed symbols.

SYMBOLS TRIGGERING MULTIPLE SYMBOL EVALUATIONS

BACKGROUND

The present disclosure relates to symbols triggering multiple symbol evaluations in gaming environments.

Gaming machines may provide players awards in primary games. Gaming machines generally require the player to place or make a wager to activate the primary or base game. The award may be based on the player obtaining a winning symbol or symbol combination and on the amount of the wager.

BRIEF SUMMARY

In various embodiments, the present disclosure relates to a gaming system including a processor and a memory device that stores a plurality of instructions that, when executed by the processor, for a play of a game, cause the processor to: cause a display, by a display device, of symbols at symbol display positions, the displayed symbols randomly selected from different symbols, the displayed symbols including a multi-evaluation trigger symbol, wherein the display of the multi-evaluation trigger symbol include a display of different alternative symbols of the multi-evaluation trigger symbol and an indication of a first one of the alternative symbols; and cause a display, by the display device, of an indication of any winning symbol combination formed by the displayed symbols and based on a first symbol evaluation including the indicated first alternative symbol of the multi-evaluation trigger symbol. The plurality of instructions, when executed by the processor, further cause the processor to cause: a display, by the display device, of an indication of a second one of the alternative symbols of the multi-evaluation trigger symbol; and cause a display, by the display device, of an indication of any winning symbol combination formed by the displayed symbols and based on a second symbol evaluation including the indicated second alternative symbol of the multi-evaluation trigger symbol. The plurality of instructions, when executed by the processor, further cause the processor to: cause a display, by the display device, of an indication of a third one of the alternative symbols of the multi-evaluation trigger symbol; and cause a display, by the display device, of an indication of any winning symbol combination formed by the displayed symbols and based on a third evaluation including the indicated third alternative symbol of the multi-evaluation trigger symbol.

In various other embodiments, the present disclosure relates to a gaming system including a processor and a memory device that stores a plurality of instructions that, when executed by the processor, for a play of a game, cause the processor to: cause a display, by a display device, of symbols at a symbol display positions, the displayed symbols randomly selected from different symbols, the displayed symbols including a plurality of multi-evaluation trigger symbols, wherein the display of each of the multi-evaluation trigger symbols includes a display of alternative symbols of that multi-evaluation trigger symbol and an indication of a first one of the alternative symbols of that multi-evaluation trigger symbol; and cause a display, by the display device, of an indication of any winning symbol combinations formed by the displayed symbols and based on one or more symbol evaluations including the indicated first alternative symbols of each of the multi-evaluation trigger symbols. The plurality of instructions, when executed by the

processor, further cause the processor to: cause a display, by the display device, of indications of second ones of the alternative symbols of each of the multi-evaluation trigger symbols; and cause a display, by the display device, of an indication of any winning symbol combinations formed by the displayed symbols and based on one or more symbol evaluations including the indicated second alternative symbols of the multi-evaluation trigger symbols. The plurality of instructions, when executed by the processor, further cause the processor to: cause a display, by the display device, of indications of third ones of the alternative symbols of each of the multi-evaluation trigger symbols; and cause a display, by the display device, of an indication of any winning symbol combinations formed by the displayed symbols and based on one or more symbol evaluations including the indicated third alternative symbols of the multi-evaluation trigger symbols.

In various other embodiments, the present disclosure relates to a gaming system including a processor and a memory device that stores a plurality of instructions that, when executed by the processor, for a play of a game, cause the processor to: cause a display, by a display device, of symbols at a symbol display positions, the displayed symbols randomly selected from different symbols, the displayed symbols including a first multi-evaluation trigger symbol and a second first multi-evaluation trigger symbol, wherein the display of the first multi-evaluation trigger symbol include a display of alternative symbols of the first multi-evaluation trigger symbol and an indication of a first one of the alternative symbols of the first multi-evaluation trigger symbol, and wherein the display of the second multi-evaluation trigger symbol includes a display of alternative symbols of the second multi-evaluation trigger symbol and an indication of a first one of the alternative symbols of the second multi-evaluation trigger symbol; and cause a display, by the display device, of an indication of any winning symbol combination formed by the displayed symbols and based on a first symbol evaluation including the indicated alternative symbol of the first multi-evaluation trigger symbol. The plurality of instructions, when executed by the processor, further cause the processor to: cause a display, by the display device, of an indication of any winning symbol combination formed by the displayed symbols and based on a second symbol evaluation including the indicated alternative symbol of the second multi-evaluation trigger symbol; and cause a display, by the display device, of an indication of a second one of the alternative symbols of the first multi-evaluation trigger symbol. The plurality of instructions, when executed by the processor, further cause the processor to: cause a display, by the display device, of an indication of any winning symbol combination formed by the displayed symbols and based on a third symbol evaluation including the indicated alternative symbol of the first multi-evaluation trigger symbol; cause a display, by the display device, of an indication of a second one of the alternative symbols of the second multi-evaluation trigger symbol; and cause a display, by the display device, of an indication of any winning symbol combination formed by the displayed symbols and based on a fourth symbol evaluation including the indicated alternative symbol of the second multi-evaluation trigger symbol.

Additional features are described herein and will be apparent from the following Detailed Description and the figures.

BRIEF DESCRIPTION OF SEVERAL VIEWS OF THE DRAWINGS

FIG. 1 is a flow chart an example process for operating a gaming system that includes symbols that trigger multiple symbol evaluations.

FIGS. 2A, 2B, and 2C are front views of example screens displays of parts of a play of a slot game including symbols that trigger multiple symbol evaluations displayed by a gaming system of one example embodiment of the present disclosure.

FIGS. 3A, 3B, and 3C are front views of example screens displays of parts of a play of a slot game including symbols that trigger multiple symbol evaluations displayed by a gaming system of another example embodiment of the present disclosure.

FIG. 4A is a front view of an example screen display of part of a play of a slot game including symbols that trigger multiple symbol evaluations displayed by a gaming system of another example embodiment of the present disclosure.

FIG. 5A is a front view of an example screen display of part of a play of a slot game including symbols that trigger multiple symbol evaluations displayed by a gaming system of another example embodiment of the present disclosure.

FIG. 6A is a front view of an example screen display of part of a play of a slot game including symbols that trigger multiple symbol evaluations displayed by a gaming system of another example embodiment of the present disclosure.

FIG. 7A is a front view of an example screen display of part of a play of a slot game including symbols that trigger multiple symbol evaluations displayed by a gaming system of another example embodiment of the present disclosure.

FIG. 8 is a front view different example symbols that trigger multiple symbol evaluations of various example embodiments of the present disclosure.

FIG. 9 is a schematic block diagram of one embodiment of an electronic configuration of an example electronic gaming machine of the present disclosure.

FIGS. 10A and 10B are perspective views of example alternative embodiments of an electronic gaming machine of the present disclosure.

FIG. 10C is a front view of an example personal gaming device of the present disclosure.

DETAILED DESCRIPTION

In various embodiments, the present disclosure relates to gaming systems and methods that include one or more symbols that trigger multiple symbol evaluations for a play of a game. These symbols are referred to herein as multi-evaluation trigger symbols or trigger symbols. In various embodiments, each of the trigger symbols can cause the gaming system and method to provide multiple independent symbol evaluations during a play of the game for the same set of randomly generated and displayed symbols.

In various embodiments, the game is a slot game including a plurality of reels and a plurality of different symbols on the reels, wherein one or more of the symbols on one or more of the reels is/are multi-evaluation trigger symbols. In various embodiments, the symbols on the reels include two or more different multi-evaluation trigger symbols. In various such embodiments, all of the symbols on one or more of the reels are multi-evaluation trigger symbols.

In various embodiments, for a play of the slot game including the plurality of reels, the gaming system randomly determines and displays a game outcome including a plurality of randomly determined symbols on the reels at a

plurality of symbol display positions. The gaming system then performs one or more evaluations of the symbols displayed at the symbol display positions to determine any winning symbols or winning symbol combinations and the awards resulting from such evaluations for the play of the slot game. The gaming system displays respective indications of each such evaluation, each such winning symbol and winning symbol combination, and each such award. For the play of the slot game, if any multi-evaluation trigger symbols are displayed at any of the symbol display positions, the gaming system performs multiple symbol evaluations wherein each symbol evaluation includes: (1) for one or more multi-evaluation trigger symbols, selecting one of the alternative symbols of that trigger symbol; (2) displaying an indication of that selected alternative symbol; and (3) conducting the award evaluation of the displayed symbols including that selected alternative symbol of the trigger symbol for that play of the slot game. Thus, in various embodiments, the quantity of award evaluations can vary based on the quantity of multi-evaluation trigger symbols displayed at any of the symbol display positions and the quantity of alternative symbols of each such displayed multi-evaluation trigger symbol. For example, if one multi-evaluation trigger symbol is displayed at a symbol display position and that multi-evaluation trigger symbol includes three alternative symbols, then the gaming system conducts three symbol evaluations where each of the three symbol evaluations includes a different one of the alternative symbols. Thus, the quantity of alternative symbols of each multi-evaluation trigger symbol determines the quantity of symbol evaluations, and thus triggers each of such symbol evaluations.

While various embodiments described herein are directed to multi-evaluation trigger symbols in association with one or more plays of a primary game (such as a primary wagering slot game), it should be appreciated that such embodiments can additionally or alternatively be employed in association with multi-evaluation trigger symbols in association with one or more plays of a secondary game (such as but not limited to free games).

While the example embodiments described herein are directed to multi-evaluation trigger symbols in plays of a slot game, it should be appreciated that such embodiments can be alternatively employed in association with multi-evaluation trigger symbols in association with non-slot games, such as, but not limited to, card games, keno games, or bingo games.

While various embodiments described below are directed to the gaming system providing multi-evaluation trigger symbols that are displayed by an electronic gaming machine ("EGM") in the form of a slot machine, it should be appreciated that such embodiments can additionally or alternatively be employed in association with a gaming system providing multi-evaluation trigger symbols that are displayed by a video poker machine, a video lottery terminal, a terminal associated with an electronic table game, a terminal associated with a live table game, a video keno machine, a video bingo machine, a sports betting terminal that also offers sports betting opportunities, a personal gaming device such as a desktop computer, a laptop computer, a tablet computer or computing device, a personal digital assistant, a mobile telephone, and/or other mobile computing device that offer plays of games (and in certain instances, sports betting opportunities).

While various embodiments described herein relate to the gaming system displaying a credit balance, a wager, and any awards as an amount of monetary credits or currency, in

other embodiments, one or more of such credit balance, such wager, and any awards provided to such a player can be for non-monetary credits, promotional credits, and/or player tracking points or credits.

FIG. 1 is a flowchart of an example process or method 100 of operating the gaming system of the present disclosure. In various embodiments, the process is represented by a set of instructions stored in one or more memories and executed by one or more processors. Although the process is described with reference to the flowchart shown in FIG. 1, many other processes of performing the acts associated with this illustrated process may be employed. For example, the order of certain of the illustrated blocks or diamonds can be changed, certain of the illustrated blocks or diamonds can be optional, or certain of the illustrated blocks or diamonds may not be employed.

Responsive to an occurrence of a slot game triggering event, the gaming system triggers a play of a slot game, as indicated in block 110. In various embodiments wherein the slot game is provided as a primary wagering game, the slot game triggering event occurs upon a placement of a wager by a player on the play of the slot game. In various embodiments wherein the slot game is a secondary game, the slot game triggering event occurs based on a displayed event associated with a play of a primary wagering game. In various embodiments wherein the slot game is a secondary game, the slot game triggering event occurs based on an event independent of any displayed event associated with the play of the primary wagering game.

For the play of the slot game, the gaming system randomly determines and then displays a plurality of symbols on a plurality of reels at a plurality of symbol display positions associated with the reels, as indicated in block 120. In various embodiments, where the symbols include one or more multi-evaluation trigger symbols but not all of the symbols are multi-evaluation trigger symbols, the gaming system can display zero, one, or more of the multi-evaluation trigger symbols at the symbol display positions for the play of the slot game.

The gaming system determines if the displayed symbols includes any multi-evaluation trigger symbols, as indicated by diamond 130.

Responsive to not displaying any multi-evaluation trigger symbols, the gaming system performs one evaluation of the displayed symbols of the play of the slot game, determines any awards associated with the displayed symbols for the play of the slot game, displays any determined any awards associated with the displayed symbols for the play of the slot game, and provides any determined awards to the player, as indicated by block 140. The gaming system then returns to block 110 and awaits the next occurrence of a slot game triggering event.

Responsive to displaying any multi-evaluation trigger symbols, the gaming system performs multiple symbol evaluations of the displayed symbols of the play of the slot game, and for each symbol evaluation, determines any awards associated with the displayed symbols for the play of the slot game, displays any determined any awards associated with the displayed symbols for the play of the slot game, and provides any determined awards to the player, as indicated by block 150. In various embodiments, for each such symbol evaluation including at least one of the multi-evaluation trigger symbol, the gaming system causes the display of at least one of the multi-evaluation trigger symbols changing to indicate the alternative symbol thereof being evaluated for that multi-evaluation trigger symbol. As mentioned above, the quantity of award evaluations varies

based on the quantity of multi-evaluation trigger symbols displayed at any of the symbol display positions and the quantity of alternative symbols of each such displayed multi-evaluation trigger symbol. The gaming system then returns to block 110 and awaits the next occurrence of a slot game triggering event.

In these various embodiments, the gaming system determines any awards associated with the displayed symbols based on: (1) the payable for the play of the slot game; (2) the wager for the play of the slot game; and (3) one of a plurality of different symbol evaluation methods. These symbols evaluation methods can, for example, include a payline symbol evaluation method, a ways to win symbol evaluation method, and/or or a scatter pay symbol evaluation method. The gaming system determines any awards based on the payable, wager, the specific evaluation method, and the displayed symbols. As part of this award determination, the gaming system can determine the symbols that are part of any winning symbol combinations. As part of this award determination and display by the gaming system, the gaming system can display a corresponding award for each winning symbol combination.

FIGS. 2A, 2B, 2C, 3A, 3B, 3C, 4A, 5A, 6A, and 7A, illustrate screen displays of parts of example plays of example primary wagering slot games of various different embodiment of the present disclosure that are each displayed on a gaming system such as an EGM (such as an EGM described below).

For these examples, the EGM displays via display device 200 (such as a display device described below) adjacently arranged video reels 210, 220, 230, 240, and 250 and different symbols (not labeled) on the video reels 210, 220, 230, 240, and 250. For each play of the slot game, the reels 210, 220, 230, 240, and 250 are configured to spin, stop spinning, and display a plurality of different symbols at respective symbol display positions (not labeled). The different symbols can include one or more multi-evaluation trigger symbols such as described in the various different embodiments. The reels 210, 220, 230, 240, and 250 are configured to cause for each displayed multi-evaluation trigger symbol, a display of an indication of which alternative symbol of that multi-evaluation trigger symbol is indicated at that point in time for evaluation, such as further described below. In various embodiments, the reels are mechanical reels, and the gaming system causes each reel to physically spin and stop spinning for each play of the game. In various such embodiments, the EGM can, for instance, use lights to display of an indication of which alternative symbol of that multi-evaluation trigger symbol is indicated at that point in time for evaluation. In various other embodiments, the reels are video reels that are displayed by a video display device of the EGM and the EGM causes the display device to display of an indication of which alternative symbol of that multi-evaluation trigger symbol is indicated at that point in time for evaluation. This can be done in a variety of different manners. In the examples provided herein, this is done by partially rotating the alternative symbols of that multi-evaluation trigger symbol and changing part of a portion such as the central portion of the multi-evaluation trigger symbol. The present disclosure contemplates that this can be displayed in alternative suitable manners.

It should be appreciated that these displays can vary in accordance with the present disclosure, and that the EGM can cause the display of additional game play related information. For example, the EGM can cause the display device to display: (1) a credit meter that displays the player's credit

balance; (2) a wager display that displays any wagers placed on plays of the primary wagering slot game; (3) a win display that displays any awards won for each play of the primary wagering slot game; and (4) a message box configured to display messages before, during, or after each play of each game. In various embodiments, the EGM indicates the player's credit balance, the player's wager, and any awards provided to the player in the form of amounts of credits; however, it should be appreciated that such indications can alternatively or additionally be made in the form of amounts of currency, points, or the like.

More specifically, FIGS. 2A, 2B, and 2C show parts of a first example play of a primary wagering slot game that has been triggered on the EGM.

FIG. 2A shows that the EGM has randomly determined and displayed a plurality of symbols (not individually labeled) on the reels 210, 220, 230, 240, and 250 at respective symbol display positions (not individually labeled). In this example, one multi-evaluation trigger symbol 310 is displayed on reel 210 along the first payline PL1. In this example, the multi-evaluation trigger symbol 310 includes three different alternative symbols (e.g., A, J, and K), and thus triggers three symbol evaluations in this example embodiment. The multi-evaluation trigger symbol 310 also includes an indication in the middle of which of three alternative symbols is currently ready for evaluation or being evaluated. In FIG. 2A, the A symbol is being evaluated for the multi-evaluation trigger symbol 310 and the indication in the middle indicates that the A symbol is being evaluated. For this first evaluation, the EGM determines that the symbol combination (A-K-K-K-K) is not a winning symbol combination and results in no award for the player.

FIG. 2B shows that the multi-evaluation trigger symbol 310 has been rotated such that the J symbol ready for evaluation and an indication in the middle of which of the three alternative symbols is currently being evaluated. In FIG. 2B, the J symbol is being evaluated for the multi-evaluation trigger symbol 310 and the indication in the middle indicates that the J symbol is being evaluated. For this second evaluation, the EGM determines that the symbol combination (J-K-K-K-K) is not a winning symbol combination and results in no award for the player.

FIG. 2C shows that the multi-evaluation trigger symbol 310 has been rotated such that the K symbol ready for evaluation and an indication in the middle of which of the three alternative symbols is currently being evaluated. In FIG. 2C, the K symbol is being evaluated for the multi-evaluation trigger symbol 310 and the indication in the middle indicates that the K symbol is being evaluated. For this third evaluation, the EGM determines that the symbol combination (K-K-K-K-K) is a winning symbol combination and results in an award of 1000 credits for the player (which can be displayed to the player).

This example shows that the example multi-evaluation trigger symbol 310 includes three different alternative symbols. In other embodiments, the quantity of symbols of the multi-evaluation trigger symbol can vary.

This example shows that the example multi-evaluation trigger symbol 310 includes a rotational arrangement and display of the different alternative symbols of the multi-evaluation trigger symbol 310. In other embodiments, the arrangement and display of the different alternative symbols of the multi-evaluation trigger symbol can vary.

This example shows that the example multi-evaluation trigger symbol 310 includes an order of indication and an order of evaluation of the different alternative symbols of the multi-evaluation trigger symbol 310. In other embodiments,

the order of indication and/or the order of evaluation of alternative symbols of the multi-evaluation trigger symbol can vary. In certain such embodiments, the order of indication and/or order of evaluation is predetermined. In certain such embodiments, the order of indication and/or the order of evaluation is randomly determined. In certain embodiments, the quantity of indications and/or the quantity of evaluation can vary based on the quantity of alternative symbols. For example, each of the alternative symbols can be sequentially indicated and evaluated. In other examples less than all of the alternative symbols can be sequentially indicated and evaluated. This illustrated example shows that the single multi-evaluation trigger symbol 310 triggered three separate indications and evaluations based on the three alternative symbols of the multi-evaluation trigger symbol 310. It should be appreciated that in other embodiments, the EGM can determine the quantity of evaluations in other suitable manners. It should also be appreciated that in various embodiment, the quantity of the rotations of the alternative symbols of the multi-evaluation trigger symbol can be more than a quantity of the alternative symbols of the multi-evaluation trigger symbol. In such embodiments, one or more of the alternative symbols can be indicated more than once.

FIGS. 3A, 3B, and 3C show parts of another example play of a primary wagering slot game that has been triggered on the EGM.

FIG. 3A shows that the EGM has randomly determined and displayed a plurality of symbols (not individually labeled) on the reels 210, 220, 230, 240, and 250 at respective symbol display positions (not individually labeled). In this example, five multi-evaluation trigger symbols 310, 320, 330, 340, and 350 are respectively displayed on reels 210, 220, 230, 240, and 250 along the first payline PL1. In this example, the multi-evaluation trigger symbols 310, 320, 330, 340, and 350 each includes three different alternative symbols (e.g., A, J, and K) and an indication in the middle of which of three alternative symbols is currently being evaluated. In this example, the multi-evaluation trigger symbols 310 and 320 are the same, and each of the multi-evaluation trigger symbols 330, 340, and 350 are each different. This example shows that two or more of the multi-evaluation trigger symbols can be different, although it should be appreciated that in certain embodiments, all of the multi-evaluation trigger symbols can be the same. This example shows that two or more of the multi-evaluation trigger symbols can be different in the different alternative symbols that comprise such multi-evaluation trigger symbols.

In various embodiments, when more than one multi-evaluation trigger symbol occurs in a play of the slot game, the rotational order and the evaluation order can be predetermined for the alternative symbols of the multi-evaluation trigger symbols. In various other embodiments, when more than one multi-evaluation trigger symbol occurs in a play of the slot game, the rotational order and the evaluation order can be randomly determined for one or more of the multi-evaluation trigger symbols.

In various embodiments, the direction of rotations of the alternative symbols of each of the multi-evaluation trigger symbols can all be in a same direction for the multiple evaluations. In various other embodiments, the direction of the rotations of each of the multi-evaluation trigger symbols can be in different directions for the multiple evaluations. In various other embodiments, one or more of the multi-evaluation trigger symbols can each rotate in multiple different directions for the multiple evaluations.

In various embodiments, the rotations of the multi-evaluation trigger symbols and associated evaluations can all be at the same time. In various other embodiments, the rotations of the multi-evaluation trigger symbols and associated evaluations can be at two or more multiple different times.

In various different embodiments, the quantity of evaluations based on the multi-evaluation trigger symbols can vary substantially in accordance with the present disclosure. For example with reference to FIG. 3A, in various different embodiments, the quantity of evaluations can be based on: (1) just one of the multi-evaluation trigger symbols 310, 320, 330, 340, and 350 (and thus the quantity of evaluations can be 3 evaluations); (2) two of the multi-evaluation trigger symbols 310, 320, 330, 340, and 350 (and thus the quantity of evaluations can be 9 evaluations); (3) three of the multi-evaluation trigger symbols 310, 320, 330, 340, and 350 (and thus the quantity of evaluations can be 81 evaluations); (4) four of the multi-evaluation trigger symbols 310, 320, 330, 340, and 350 (and thus the quantity of evaluations can be 324 evaluations); or (5) five of the multi-evaluation trigger symbols 310, 320, 330, 340, and 350 (and thus the quantity of evaluations can be 972 evaluations). In these examples, the rotations of the multi-evaluation trigger symbols 310, 320, 330, 340, and 350 are at different times. In various embodiments, any suitable sub-set of such evaluations or combinations thereof can be provided. In various different embodiments, the sub-sets can be predetermined or randomly determined.

In various embodiments, the starting rotational order of each multi-evaluation trigger symbol when it is first displayed can be determined independent of each of the other multi-evaluation trigger symbols. This starting rotational order for each multi-evaluation trigger symbol can be predetermined, randomly determined, determined based on a past occurrence of that multi-evaluation trigger symbol, or determined in another suitable manner.

In FIG. 3A, (1) the A symbol is being evaluated for the multi-evaluation trigger symbol 310 and the indication in the middle indicates that the A symbol is being evaluated; (2) the A symbol is being evaluated for the multi-evaluation trigger symbol 320 and the indication in the middle indicates that the A symbol is being evaluated; (3) the A symbol is being evaluated for the multi-evaluation trigger symbol 330 and the indication in the middle indicates that the A symbol is being evaluated; (4) the J symbol is being evaluated for the multi-evaluation trigger symbol 340 and the indication in the middle indicates that the J symbol is being evaluated; and (5) the Q symbol is being evaluated for the multi-evaluation trigger symbol 350 and the indication in the middle indicates that the Q symbol is being evaluated. For this first evaluation, the EGM determines that the symbol combination (A-A-A) is a winning symbol combination and results in an award of 300 credits for the player.

FIG. 3B shows an example point in the play of the slot game and specifically a subsequent evaluation where: (1) the multi-evaluation trigger symbol 310 has been rotated one position clockwise such that the J symbol is being evaluated and an indication in the middle that indicates that the J symbol is being evaluated; (2) the multi-evaluation trigger symbol 320 has been rotated one position clockwise such that the J symbol is being evaluated and an indication in the middle that indicates that the J symbol is being evaluated; (3) the multi-evaluation trigger symbol 330 has been rotated two positions clockwise (or one position counter-clockwise) such that the J symbol is being evaluated and an indication in the middle that indicates that the J symbol is being evaluated; (4) the multi-evaluation trigger symbol 340 has

not been rotated; and (5) the multi-evaluation trigger symbol 350 has been rotated. For this subsequent evaluation, the EGM determines that the symbol combination (J-J-J) is a winning symbol combination and results in an award of 500 credits for the player. The example shows that the rotations can be different for the multi-evaluation trigger symbols and that one or more of the multi-evaluation trigger symbols can remain stationary. These rotations can be on a predetermined basis or a randomly determined basis for one or more or each of the multi-evaluation trigger symbols. Thus, for one example embodiment, to determine the positions of the multi-evaluation trigger symbols 310, 320, 330, 340, and 350 in FIG. 3B, the EGM randomly determines to: (1) rotate the multi-evaluation trigger symbol 310 one position; (2) rotate the multi-evaluation trigger symbol 320 one position; (3) rotate the multi-evaluation trigger symbol 330 two positions; (4) not rotate the multi-evaluation trigger symbol 340; and (5) not rotate the multi-evaluation trigger symbol 350. This example shows how the determinations of the positions and evaluations of the multi-evaluation trigger symbols can vary in accordance with the present disclosure.

FIG. 3C shows another example point in the play of the slot game and specifically a subsequent evaluation where: (1) the multi-evaluation trigger symbol 310 has been rotated one position clockwise such that the K symbol is being evaluated and an indication in the middle that indicates that the K symbol is being evaluated; (2) the multi-evaluation trigger symbol 320 has been rotated one position clockwise such that the K symbol is being evaluated and an indication in the middle that indicates that the K symbol is being evaluated; (3) the multi-evaluation trigger symbol 330 has not been rotated such that the J symbol is being evaluated and an indication in the middle that indicates that the J symbol is being evaluated; (4) the multi-evaluation trigger symbol 340 has been rotated two positions clockwise such that the K symbol is being evaluated and an indication in the middle that indicates that the K symbol is being evaluated; and (5) the multi-evaluation trigger symbol 350 has been rotated two positions clockwise such that the A symbol is being evaluated and an indication in the middle that indicates that the A symbol is being evaluated. For this subsequent evaluation, the EGM determines that the no winning symbol combinations are formed and thus does not provide any additional award for the player. This example also shows that the rotations can be different for the multi-evaluation trigger symbols and that one or more of the multi-evaluation trigger symbols can remain stationary. As indicated above these rotations can be on a predetermined basis or a randomly determined basis for one or more or each of the multi-evaluation trigger symbols. This example further shows how the determinations of the positions and evaluations of the multi-evaluation trigger symbols can vary in accordance with the present disclosure.

FIG. 4A shows a part of another example play of a primary wagering slot game that has been triggered on the EGM. FIG. 4A shows that the EGM has randomly determined and displayed a plurality of symbols (not individually labeled) on the reels 210, 220, 230, 240, and 250 at respective symbol display positions (not individually labeled). In this example, four identical multi-evaluation trigger symbols 310, 320, 330, and 340 are respectively displayed on reels 210, 220, 230, and 240 along the first payline PL1. In this example, the multi-evaluation trigger symbols 310, 320, 330, and 340 each includes three different alternative symbols (e.g., A, J, and K) and an indication in the middle of which of three alternative symbols is currently being evaluated. In this example, the multi-evaluation trigger symbols

310, 320, 320, and 340 are all the same, and all start in the same rotational position. For this first evaluation, the EGM determines that the symbol combination (A-A-A-A) is a winning symbol combination and results in an award of 800 credits for the player.

FIG. 5A shows a part of another example play of a primary wagering slot game that has been triggered on the EGM. FIG. 5A shows that the EGM has randomly determined and displayed a plurality of symbols (not individually labeled) on the reels 210, 220, 230, 240, and 250 at respective symbol display positions (not individually labeled). In this example, four identical multi-evaluation trigger symbols 310, 320, 330, and 350 are respectively displayed on reels 210, 220, 230, and 240 along different paylines (not indicated). In this example, the multi-evaluation trigger symbols 310, 320, 330, and 350 each includes three different alternative symbols (e.g., A, J, and K) and an indication in the middle of which of three alternative symbols is currently being evaluated. In this example, the multi-evaluation trigger symbols 310, 320, 320, and 350 are all the same, and all start in the same rotational position. The EGM can determine for each different payline any awards. In this example, each of the multi-evaluation trigger symbols 310, 320, 330, and 350 causes three symbol evaluations for each row or payline.

FIG. 6A shows a part of another example play of a primary wagering slot game that has been triggered on the EGM. FIG. 6A shows that the EGM has randomly determined and displayed a plurality of symbols (not individually labeled) on the reels 210, 220, 230, 240, and 250 at respective symbol display positions (not individually labeled). In this example, three identical multi-evaluation trigger symbols 310, 330, and 350 are respectively displayed on reels 210, 230, and 250 along the first payline (not indicated). In this example, the multi-evaluation trigger symbols 310, 320, 330, and 350 each includes three different alternative symbols (e.g., A, J, and Wild) and an indication in the middle of which of three alternative symbols is currently being evaluated. In this example, the multi-evaluation trigger symbols 310, 330, and 350 are all the same, and all start in the same rotational position. This example shows that other types of symbols (such as wild symbols) can be part of one or more of the multi-evaluation trigger symbols.

FIG. 7A shows a part of another example play of a primary wagering slot game that has been triggered on the EGM. FIG. 7A shows that the EGM has randomly determined and displayed a plurality of symbols (not individually labeled) on the reels 210, 220, 230, 240, and 250 at respective symbol display positions (not individually labeled). In this example, two identical multi-evaluation trigger symbols 360 and 370 are respectively displayed on reels 210 and 230 the respective paylines (not indicated). In this example, each of the multi-evaluation trigger symbols 360 and 370 includes five alternative symbols and an indication in the middle of which of the alternative symbols is currently being evaluated. In this example, the multi-evaluation trigger symbols 360 and 370 are all the same and start in the same rotational position. This example shows that other quantities and types of alternative symbols can form one or more of the multi-evaluation trigger symbols. In this example embodiment, the FG alternative symbols stand for free games, and during one of the evaluations associated with one of the rotations of both of the multi-evaluation trigger symbols 360 and 370, the symbol combination of FG-FG-FG would occur, and the EGM would provide a series of free plays of the slot game.

In various embodiments, the EGM can change the form (such as the color) of one or more of the multi-evaluation trigger symbols and can cause additional quantities of symbol evaluations based on such changed form. For example, 5 a change in form can cause another full set of evaluations or any suitable additional quantity of evaluations.

FIG. 8 also shows different forms of multi-evaluation trigger symbols with different quantities of alternative symbols and different alternative symbols. FIG. 8 also shows 10 that modifiers such as different multipliers can be associated with one or more of the different multi-evaluation trigger symbols. In various embodiments, the symbols of the multi-evaluation trigger symbols, the quantities of the alternative symbols of the multi-evaluation trigger symbols, and such 15 modifiers can be determined or based on one or more factors such as but not limited to wager and/or denomination levels, and random determinations. The modifiers (such as the multipliers) can be used to increase awards that are determined based on the associated symbol. In other embodiments, the 1x, 2x, 3x, 4x, and 5x in FIG. 8 can represent 20 respective quantities of rotations associated with each multi-evaluation trigger symbols. Thus, such 1x to 5x indicators can related to a quantity of rotations or a multiplier.

It should be appreciated from the above, that in various 25 embodiments, the gaming system can exhaust all combinations by rotating through each of the alternative symbols of each multi-evaluation trigger symbols. In various other 30 embodiments, where multi-evaluation trigger symbols with different quantities of alternative symbols are displayed, 35 different quantities of evaluations can be employed. For example, if two multi-evaluation trigger symbols are displayed on the reels where one multi-evaluation trigger symbol has three alternative symbols and one multi-evaluation trigger symbols has five alternative symbols, the 40 gaming system can perform all five rotations, and the multi-evaluation trigger symbol with three alternative symbols can keep looping through its alternative symbols to keep up with the five alternative symbols of the other multi-evaluation trigger symbol. In other embodiments, the last alternative symbol of the three alternative symbol multi-evaluation symbol can remain for the additional evaluations of the five alternative symbol multi-evaluation symbol.

It should also be appreciated from the above that the 45 rotational layout of the alternative symbols of the multi-evaluation trigger symbols can vary in accordance with the present disclosure.

It should further be appreciated from the above that in 50 various embodiments, the present disclosure relates to gaming systems and methods that, for a play of a game: cause a display of symbols at symbol display positions, the displayed symbols randomly selected from different symbols, the displayed symbols including a multi-evaluation trigger symbol, wherein the display of the multi-evaluation trigger symbol include a display of different alternative symbols of 55 the multi-evaluation trigger symbol and an indication of a first one of the alternative symbols; cause a display of an indication of any winning symbol combination formed by the displayed symbols and based on a first symbol evaluation including the indicated first alternative symbol of the 60 multi-evaluation trigger symbol; cause a display of an indication of a second one of the alternative symbols of the multi-evaluation trigger symbol; cause a display of an indication of any winning symbol combination formed by the displayed symbols and based on a second symbol evaluation including the indicated second alternative symbol of the 65 multi-evaluation trigger symbol; cause a display of an indication of a third one of the alternative symbols of the

13

multi-evaluation trigger symbol; and cause a display of an indication of any winning symbol combination formed by the displayed symbols and based on a third evaluation including the indicated third alternative symbol of the multi-evaluation trigger symbol. In various such embodiments, the gaming system and method cause a display of a first rotation of the alternative symbols of the multi-evaluation trigger symbol associated with the display of the indication of the second one of the alternative symbols of the multi-evaluation trigger symbol. In various such embodiments, the gaming system and method cause a display of the first rotation of the alternative symbols of the multi-evaluation trigger symbol is based on a predetermined direction of rotation. In various such embodiments, the gaming system and method cause a display of a second rotation of the alternative symbols of the multi-evaluation trigger symbol associated with the display of the indication of the third one of the alternative symbols of the multi-evaluation trigger symbol. In various such embodiments, a quantity of the rotations of the alternative symbols of the multi-evaluation trigger symbol is less than a quantity of the alternative symbols of the multi-evaluation trigger symbol. In various such embodiments, a quantity of the rotations of the alternative symbols of the multi-evaluation trigger symbol is more than a quantity of the alternative symbols of the multi-evaluation trigger symbol. In various such embodiments, the gaming system and method cause a display of an indication of a quantity of rotations of the multi-evaluation trigger symbol.

It should further be appreciated from the above that in various embodiments, the present disclosure relates to gaming systems and methods that, for a play of a game: cause a display of symbols at a symbol display positions, the displayed symbols randomly selected from different symbols, the displayed symbols including a plurality of multi-evaluation trigger symbols, wherein the display of each of the multi-evaluation trigger symbols includes a display of alternative symbols of that multi-evaluation trigger symbol and an indication of a first one of the alternative symbols of that multi-evaluation trigger symbol; cause a display of an indication of any winning symbol combinations formed by the displayed symbols and based on one or more symbol evaluations including the indicated first alternative symbols of each of the multi-evaluation trigger symbols; cause a display of indications of second ones of the alternative symbols of each of the multi-evaluation trigger symbols; cause a display of an indication of any winning symbol combinations formed by the displayed symbols and based on one or more symbol evaluations including the indicated second alternative symbols of the multi-evaluation trigger symbols; cause a display of indications of third ones of the alternative symbols of each of the multi-evaluation trigger symbols; and cause a display of an indication of any winning symbol combinations formed by the displayed symbols and based on one or more symbol evaluations including the indicated third alternative symbols of the multi-evaluation trigger symbols. In various such embodiments, the gaming system and method cause a display of first rotations of the alternative symbols of the multi-evaluation trigger symbols associated with the displays of the indication of the second ones of the alternative symbols of the multi-evaluation trigger symbols. In various such embodiments, the gaming system and method cause a display of second rotations of the alternative symbols of the multi-evaluation trigger symbols associated with the displays of the indications of the third ones of the alternative symbols of the multi-evaluation trigger symbols. In various such embodiments, the gaming

14

system and method cause a display of the first rotations of the alternative symbols of the multi-evaluation trigger symbols and the indication of the second ones of the alternative symbols of the multi-evaluation trigger symbols based on 5 predetermined directions of rotation. In various such embodiments, the predetermined directions of rotation are a same direction of rotation. In various such embodiments, each of the multi-evaluation trigger symbols only comprises the first, second, and third alternative symbols. In various 10 such embodiments, at least two of the multi-evaluation trigger symbols comprise different alternative symbols. In various such embodiments, each of the multi-evaluation trigger symbols comprise the same alternative symbols.

It should further be appreciated from the above that in 15 various embodiments, the present disclosure relates to gaming systems and methods that, for a play of a game, cause a display of symbols at a symbol display positions, the displayed symbols randomly selected from different symbols, the displayed symbols including a first multi-evaluation trigger symbol and a second first multi-evaluation trigger symbol, wherein the display of the first multi-evaluation trigger symbol include a display of alternative symbols of the first multi-evaluation trigger symbol and an indication of 20 a first one of the alternative symbols of the first multi-evaluation trigger symbol, and wherein the display of the second multi-evaluation trigger symbol includes a display of alternative symbols of the second multi-evaluation trigger symbol and an indication of a first one of the alternative symbols of the second multi-evaluation trigger symbol; 25 cause a display of an indication of any winning symbol combination formed by the displayed symbols and based on a first symbol evaluation including the indicated alternative symbol of the first multi-evaluation trigger symbol; cause a display of an indication of any winning symbol combination 30 formed by the displayed symbols and based on a second symbol evaluation including the indicated alternative symbol of the second multi-evaluation trigger symbol; cause a display of an indication of a second one of the alternative symbols of the first multi-evaluation trigger symbol; cause a display of an indication of any winning symbol combination formed by the displayed symbols and based on a third symbol evaluation including the indicated alternative symbol of the first multi-evaluation trigger symbol; cause a display of an indication of a second one of the alternative symbols of the second multi-evaluation trigger symbol; and cause a display of an indication of any winning symbol combination formed by the displayed symbols and based on a fourth symbol evaluation including the indicated alternative symbol of the second multi-evaluation trigger symbol. 35 In various such embodiments, the gaming system and method cause a display of a first rotation of the alternative symbols of the first multi-evaluation trigger symbol and a first rotation of the alternative symbols of the second multi-evaluation trigger symbol. In various such embodiments, the 40 gaming system and method cause a display of first rotations of the alternative symbols of the first and second multi-evaluation trigger symbols based on predetermined directions of rotation. In various such embodiments, the predetermined directions of rotation are a same direction of rotation. In various such embodiments, the gaming system and method cause: (1) cause a display of an indication of a third one of the alternative symbols of the first multi-evaluation trigger symbol; (2) cause a display of an indication of any winning symbol combination formed by the 45 displayed symbols and based on a fifth symbol evaluation comprising the indicated alternative symbol of the first multi-evaluation trigger symbol; (3) cause a display of an 50

indication of a third one of the alternative symbols of the second multi-evaluation trigger symbol; and (4) cause a display of an indication of any winning symbol combination formed by the displayed symbols and based on a sixth symbol evaluation comprising the indicated alternative symbol of the second multi-evaluation trigger symbol.

It should further be appreciated that in different embodiments, one or more of: which multi-evaluation trigger symbols are determined, which symbols of each multi-evaluation trigger symbol is evaluated, which order the symbols of each multi-evaluation trigger symbol is evaluated, and/or any determination disclosed herein is/are predetermined, randomly determined, randomly determined based on one or more weighted percentages, determined based on a generated symbol or symbol combination, determined independent of a generated symbol or symbol combination, determined based on a random determination by the central controller, determined independent of a random determination by the central controller, determined based on a random determination at the gaming system, determined independent of a random determination at the gaming system, determined based on at least one play of at least one game, determined independent of at least one play of at least one game, determined based on a user's selection, determined independent of a user's selection, determined based on one or more side wagers placed, determined independent of one or more side wagers placed, determined based on the user's primary game wager, determined independent of the user's primary game wager, determined based on time (such as the time of day), determined independent of time (such as the time of day), determined based on an amount of coin-in accumulated in one or more pools, determined independent of an amount of coin-in accumulated in one or more pools, determined based on a status of the user (i.e., a player tracking status), determined independent of a status of the user (i.e., a player tracking status), determined based on one or more other determinations disclosed herein, determined independent of any other determination disclosed herein or determined based on any other suitable method or criteria.

Gaming Systems

The above-described embodiments of the present disclosure can be implemented in accordance with or in conjunction with one or more of a variety of different types of gaming systems, such as, but not limited to, those described below.

The present disclosure contemplates a variety of different gaming systems each having one or more of a plurality of different features, attributes, or characteristics. A "gaming system" as used herein refers to various configurations of: (a) one or more servers; (b) one or more electronic gaming machines such as those located on a casino floor; and/or (c) one or more personal gaming devices. Thus, in various embodiments, the gaming system of the present disclosure includes: (a) one or more electronic gaming machines in combination with one or more servers; (b) one or more personal gaming devices in combination with one or more servers; (c) one or more personal gaming devices in combination with one or more electronic gaming machines; (d) one or more personal gaming devices, one or more electronic gaming machines, and one or more servers in combination with one another; (e) a single electronic gaming machine; (f) a plurality of electronic gaming machines in combination with one another; (g) a single personal gaming device; (h) a plurality of personal gaming devices in combination with one another; (i) a single server; and/or (j) a

plurality of servers in combination with one another. For brevity and clarity and unless specifically stated otherwise, "EGM" as used herein represents one EGM or a plurality of EGMs, "personal gaming device" as used herein represents one personal gaming device or a plurality of personal gaming devices, and "server" as used herein represents one server or a plurality of servers.

As noted above, in various embodiments, the gaming system includes an EGM (or personal gaming device) in combination with a server. In such embodiments, the EGM (or personal gaming device) is configured to communicate with the server through a data network or remote communication link. In certain such embodiments, the EGM (or personal gaming device) is configured to communicate with another EGM (or personal gaming device) through the same data network or remote communication link or through a different data network or remote communication link. For example, the gaming system includes a plurality of EGMs that are each configured to communicate with a server through a data network.

In certain embodiments in which the gaming system includes an EGM (or personal gaming device) in combination with a server, the server is any suitable computing device (such as a server) that includes at least one processor and at least one memory device or data storage device. As further described herein, the EGM (or personal gaming device) includes at least one EGM (or personal gaming device) processor configured to transmit and receive data or signals representing events, messages, commands, or any other suitable information between the EGM (or personal gaming device) and the server. The at least one processor of that EGM (or personal gaming device) is configured to execute the events, messages, or commands represented by such data or signals in conjunction with the operation of the EGM (or personal gaming device). Moreover, the at least one processor of the server is configured to transmit and receive data or signals representing events, messages, commands, or any other suitable information between the server and the EGM (or personal gaming device). The at least one processor of the server is configured to execute the events, messages, or commands represented by such data or signals in conjunction with the operation of the server. One, more than one, or each of the functions of the server may be performed by the at least one processor of the EGM (or personal gaming device). Further, one, more than one, or each of the functions of the at least one processor of the EGM (or personal gaming device) may be performed by the at least one processor of the server.

In certain such embodiments, computerized instructions for controlling any games (such as any primary or base games and/or any secondary or bonus games) displayed by the EGM (or personal gaming device) are executed by the server. In such "thin client" embodiments, the server remotely controls any games (or other suitable interfaces) displayed by the EGM (or personal gaming device), and the EGM (or personal gaming device) is utilized to display such games (or suitable interfaces) and to receive one or more inputs or commands. In other such embodiments, computerized instructions for controlling any games displayed by the EGM (or personal gaming device) are communicated from the server to the EGM (or personal gaming device) and are stored in at least one memory device of the EGM (or personal gaming device). In such "thick client" embodiments, the at least one processor of the EGM (or personal gaming device) executes the computerized instructions to control any games (or other suitable interfaces) displayed by the EGM (or personal gaming device).

In various embodiments in which the gaming system includes a plurality of EGMs (or personal gaming devices), one or more of the EGMs (or personal gaming devices) are thin client EGMs (or personal gaming devices) and one or more of the EGMs (or personal gaming devices) are thick client EGMs (or personal gaming devices). In other embodiments in which the gaming system includes one or more EGMs (or personal gaming devices), certain functions of one or more of the EGMs (or personal gaming devices) are implemented in a thin client environment, and certain other functions of one or more of the EGMs (or personal gaming devices) are implemented in a thick client environment. In one such embodiment in which the gaming system includes an EGM (or personal gaming device) and a server, computerized instructions for controlling any primary or base games displayed by the EGM (or personal gaming device) are communicated from the server to the EGM (or personal gaming device) in a thick client configuration, and computerized instructions for controlling any secondary or bonus games or other functions displayed by the EGM (or personal gaming device) are executed by the server in a thin client configuration.

In certain embodiments in which the gaming system includes: (a) an EGM (or personal gaming device) configured to communicate with a server through a data network; and/or (b) a plurality of EGMs (or personal gaming devices) configured to communicate with one another through a data network, the data network is a local area network (LAN) in which the EGMs (or personal gaming devices) are located substantially proximate to one another and/or the server. In one example, the EGMs (or personal gaming devices) and the server are located in a gaming establishment or a portion of a gaming establishment.

In other embodiments in which the gaming system includes: (a) an EGM (or personal gaming device) configured to communicate with a server through a data network; and/or (b) a plurality of EGMs (or personal gaming devices) configured to communicate with one another through a data network, the data network is a wide area network (WAN) in which one or more of the EGMs (or personal gaming devices) are not necessarily located substantially proximate to another one of the EGMs (or personal gaming devices) and/or the server. For example, one or more of the EGMs (or personal gaming devices) are located: (a) in an area of a gaming establishment different from an area of the gaming establishment in which the server is located; or (b) in a gaming establishment different from the gaming establishment in which the server is located. In another example, the server is not located within a gaming establishment in which the EGMs (or personal gaming devices) are located. In certain embodiments in which the data network is a WAN, the gaming system includes a server and an EGM (or personal gaming device) each located in a different gaming establishment in a same geographic area, such as a same city or a same state. Gaming systems in which the data network is a WAN are substantially identical to gaming systems in which the data network is a LAN, though the quantity of EGMs (or personal gaming devices) in such gaming systems may vary relative to one another.

In further embodiments in which the gaming system includes: (a) an EGM (or personal gaming device) configured to communicate with a server through a data network; and/or (b) a plurality of EGMs (or personal gaming devices) configured to communicate with one another through a data network, the data network is an internet (such as the Internet) or an intranet. In certain such embodiments, an Internet browser of the EGM (or personal gaming device) is usable

to access an Internet game page from any location where an Internet connection is available. In one such embodiment, after the EGM (or personal gaming device) accesses the Internet game page, the server identifies a user before enabling that user to place any wagers on any plays of any wagering games. In one example, the server identifies the user by requiring a user account of the user to be logged into via an input of a unique username and password combination assigned to the user. The server may, however, identify the user in any other suitable manner, such as by validating a player tracking identification number associated with the user; by reading a player tracking card or other smart card inserted into a card reader (as described below); by validating a unique user identification number associated with the user by the server; or by identifying the EGM (or personal gaming device), such as by identifying the MAC address or the IP address of the Internet facilitator. In various embodiments, once the server identifies the user, the server enables placement of one or more wagers on one or more plays of one or more primary or base games and/or one or more secondary or bonus games and displays those plays via the Internet browser of the EGM (or personal gaming device).

The server and the EGM (or personal gaming device) are configured to connect to the data network or remote communications link in any suitable manner. In various embodiments, such a connection is accomplished via a conventional phone line or other data transmission line, a digital subscriber line (DSL), a T-1 line, a coaxial cable, a fiber optic cable, a wireless or wired routing device, a mobile communications network connection (such as a cellular network or mobile Internet network), or any other suitable medium. The expansion in the quantity of computing devices and the quantity and speed of Internet connections in recent years increases opportunities for users to use a variety of EGMs (or personal gaming devices) to play games from an ever-increasing quantity of remote sites. Additionally, the enhanced bandwidth of digital wireless communications may render such technology suitable for some or all communications, particularly if such communications are encrypted. Higher data transmission speeds may be useful for enhancing the sophistication and response of the display and interaction with users.

FIG. 9 is a block diagram of an example EGM 1000 and FIGS. 10A and 10B include two different example EGMs 2000a and 2000b. The EGMs 1000, 2000a, and 2000b are merely example EGMs, and different EGMs may be implemented using different combinations of the components shown in the EGMs 1000, 2000a, and 2000b. Although the below refers to EGMs, in various embodiments personal gaming devices (such as personal gaming device 2000c of FIG. 10C) may include some or all of the below components.

In these embodiments, the EGM 1000 includes a master gaming controller 1012 configured to communicate with and to operate with a plurality of peripheral devices 1022.

The master gaming controller 1012 includes at least one processor 1010. The at least one processor 1010 is any suitable processing device or set of processing devices, such as a microprocessor, a microcontroller-based platform, a suitable integrated circuit, or one or more application-specific integrated circuits (ASICs), configured to execute software enabling various configuration and reconfiguration tasks, such as: (1) communicating with a remote source (such as a server that stores authentication information or game information) via a communication interface 1006 of the master gaming controller 1012; (2) converting signals read by an interface to a format corresponding to that used

by software or memory of the EGM; (3) accessing memory to configure or reconfigure game parameters in the memory according to indicia read from the EGM; (4) communicating with interfaces and the peripheral devices **1022** (such as input/output devices); and/or (5) controlling the peripheral devices **1022**. In certain embodiments, one or more components of the master gaming controller **1012** (such as the at least one processor **1010**) reside within a housing of the EGM (described below), while in other embodiments at least one component of the master gaming controller **1012** resides outside of the housing of the EGM.

The master gaming controller **1012** also includes at least one memory device **1016**, which includes: (1) volatile memory (e.g., RAM **1009**, which can include non-volatile RAM, magnetic RAM, ferroelectric RAM, and any other suitable forms); (2) non-volatile memory **1019** (e.g., disk memory, FLASH memory, EPROMs, EEPROMs, memristor-based non-volatile solid-state memory, etc.); (3) unalterable memory (e.g., EPROMs **1008**); (4) read-only memory; and/or (5) a secondary memory storage device **1015**, such as a non-volatile memory device, configured to store gaming software related information (the gaming software related information and the memory may be used to store various audio files and games not currently being used and invoked in a configuration or reconfiguration). Any other suitable magnetic, optical, and/or semiconductor memory may operate in conjunction with the EGM of the present disclosure. In certain embodiments, the at least one memory device **1016** resides within the housing of the EGM (described below), while in other embodiments at least one component of the at least one memory device **1016** resides outside of the housing of the EGM. In these embodiments, any combination of one or more computer readable media may be utilized. The computer readable media may be a computer readable signal medium or a computer readable storage medium. A computer readable storage medium may be, for example, but not limited to, an electronic, magnetic, optical, electromagnetic, or semiconductor system, apparatus, or device, or any suitable combination of the foregoing. More specific examples (a non-exhaustive list) of the computer readable storage medium would include the following: a portable computer diskette, a hard disk, a random access memory (RAM), a read-only memory (ROM), an erasable programmable read-only memory (EPROM or Flash memory), an appropriate optical fiber with a repeater, a portable compact disc read-only memory (CD-ROM), an optical storage device, a magnetic storage device, or any suitable combination of the foregoing. In the context of this document, a computer readable storage medium may be any tangible medium that can contain or store a program for use by or in connection with an instruction execution system, apparatus, or device.

A computer readable signal medium may include a propagated data signal with computer readable program code embodied therein, for example, in baseband or as part of a carrier wave. Such a propagated signal may take any of a variety of forms, including, but not limited to, electromagnetic, optical, or any suitable combination thereof. A computer readable signal medium may be any computer readable medium that is not a computer readable storage medium and that can communicate, propagate, or transport a program for use by or in connection with an instruction execution system, apparatus, or device. Program code embodied on a computer readable signal medium may be transmitted using any appropriate medium, including but not limited to wireless, wireline, optical fiber cable, RF, etc., or any suitable combination of the foregoing.

The at least one memory device **1016** is configured to store, for example: (1) configuration software **1014**, such as all the parameters and settings for a game playable on the EGM; (2) associations **1018** between configuration indicia read from an EGM with one or more parameters and settings; (3) communication protocols configured to enable the at least one processor **1010** to communicate with the peripheral devices **1022**; and/or (4) communication transport protocols (such as TCP/IP, USB, Firewire, IEEE1394, Bluetooth, IEEE 802.11x (IEEE 802.11 standards), hiperlan/2, HomeRF, etc.) configured to enable the EGM to communicate with local and non-local devices using such protocols. In one implementation, the master gaming controller **1012** communicates with other devices using a serial communication protocol. A few non-limiting examples of serial communication protocols that other devices, such as peripherals (e.g., a bill validator or a ticket printer), may use to communicate with the master game controller **1012** include USB, RS-232, and Netplex (a proprietary protocol developed by IGT).

As will be appreciated by one skilled in the art, aspects of the present disclosure may be illustrated and described herein in any of a number of patentable classes or context including any new and useful process, machine, manufacture, or composition of matter, or any new and useful improvement thereof. Accordingly, aspects of the present disclosure may be implemented entirely hardware, entirely software (including firmware, resident software, microcode, etc.) or combining software and hardware implementation that may all generally be referred to herein as a "circuit," "module," "component," or "system." Furthermore, aspects of the present disclosure may take the form of a computer program product embodied in one or more computer readable media having computer readable program code embodied thereon.

Computer program code for carrying out operations for aspects of the present disclosure may be written in any combination of one or more programming languages, including an object oriented programming language such as Java, Scala, Smalltalk, Eiffel, JADE, Emerald, C++, C#, VB.NET, Python or the like, conventional procedural programming languages, such as the "C" programming language, Visual Basic, Fortran 2003, Perl, COBOL 2002, PHP, ABAP, dynamic programming languages such as Python, Ruby and Groovy, or other programming languages. The program code may execute entirely on the user's computer, partly on the user's computer, as a stand-alone software package, partly on the user's computer and partly on a remote computer or entirely on the remote computer or server. In the latter scenario, the remote computer may be connected to the user's computer through any type of network, including a local area network (LAN) or a wide area network (WAN), or the connection may be made to an external computer (for example, through the Internet using an Internet Service Provider) or in a cloud computing environment or offered as a service such as a Software as a Service (SaaS).

Aspects of the present disclosure are described herein with reference to flowchart illustrations and/or block diagrams of methods, apparatuses (systems) and computer program products according to embodiments of the disclosure. It will be understood that each block of the flowchart illustrations and/or block diagrams, and combinations of blocks in the flowchart illustrations and/or block diagrams, can be implemented by computer program instructions. These computer program instructions may be provided to a processor of a general purpose computer, special purpose

computer, or other programmable data processing apparatus to produce a machine, such that the instructions, which execute via the processor of the computer or other programmable instruction execution apparatus, create a mechanism for implementing the functions/acts specified in the flowchart and/or block diagram block or blocks.

These computer program instructions may also be stored in a computer readable medium that when executed can direct a computer, other programmable data processing apparatus, or other devices to function in a particular manner, such that the instructions when stored in the computer readable medium produce an article of manufacture including instructions which when executed, cause a computer to implement the function/act specified in the flowchart and/or block diagram block or blocks. The computer program instructions may also be loaded onto a computer, other programmable instruction execution apparatus, or other devices to cause a series of operational steps to be performed on the computer, other programmable apparatuses or other devices to produce a computer implemented process such that the instructions which execute on the computer or other programmable apparatus provide processes for implementing the functions/acts specified in the flowchart and/or block diagram block or blocks.

In certain embodiments, the at least one memory device **1016** is configured to store program code and instructions executable by the at least one processor of the EGM to control the EGM. The at least one memory device **1016** of the EGM also stores other operating data, such as image data, event data, input data, random number generators (RNGs) or pseudo-RNGs, paytable data or information, and/or applicable game rules that relate to the play of one or more games on the EGM. In various embodiments, part, or all of the program code and/or the operating data described above is stored in at least one detachable or removable memory device including, but not limited to, a cartridge, a disk, a CD ROM, a DVD, a USB memory device, or any other suitable non-transitory computer readable medium. In certain such embodiments, an operator (such as a gaming establishment operator) and/or a user uses such a removable memory device in an EGM to implement at least part of the present disclosure. In other embodiments, part, or all of the program code and/or the operating data is downloaded to the at least one memory device of the EGM through any suitable data network described above (such as an Internet or intranet).

The at least one memory device **1016** also stores a plurality of device drivers **1042**. Examples of different types of device drivers include device drivers for EGM components and device drivers for the peripheral components **1022**. Typically, the device drivers **1042** utilize various communication protocols that enable communication with a particular physical device. The device driver abstracts the hardware implementation of that device. For example, a device driver may be written for each type of card reader that could potentially be connected to the EGM. Non-limiting examples of communication protocols used to implement the device drivers include Netplex, USB, Serial, Ethernet **175**, Firewire, I/O debouncer, direct memory map, serial, PCI, parallel, RF, Bluetooth™ near-field communications (e.g., using near-field magnetics), 802.11 (WiFi), etc. In one embodiment, when one type of a particular device is exchanged for another type of the particular device, the at least one processor of the EGM loads the new device driver from the at least one memory device to enable communication with the new device. For instance, one type of card reader in the EGM can be replaced with a second different

type of card reader when device drivers for both card readers are stored in the at least one memory device.

In certain embodiments, the software units stored in the at least one memory device **1016** can be upgraded as needed. For instance, when the at least one memory device **1016** is a hard drive, new games, new game options, new parameters, new settings for existing parameters, new settings for new parameters, new device drivers, and new communication protocols can be uploaded to the at least one memory device **1016** from the master game controller **1012** or from some other external device. As another example, when the at least one memory device **1016** includes a CD/DVD drive including a CD/DVD configured to store game options, parameters, and settings, the software stored in the at least one memory device **1016** can be upgraded by replacing a first CD/DVD with a second CD/DVD. In yet another example, when the at least one memory device **1016** uses flash memory **1019** or EPROM **1008** units configured to store games, game options, parameters, and settings, the software stored in the flash and/or EPROM memory units can be upgraded by replacing one or more memory units with new memory units that include the upgraded software. In another embodiment, one or more of the memory devices, such as the hard drive, may be employed in a game software download process from a remote software server.

In some embodiments, the at least one memory device **1016** also stores authentication and/or validation components **1044** configured to authenticate/validate specified EGM components and/or information, such as hardware components, software components, firmware components, peripheral device components, user input device components, information received from one or more user input devices, information stored in the at least one memory device **1016**, etc.

In certain embodiments, the peripheral devices **1022** include several device interfaces, such as: (1) at least one output device **1020** including at least one display device **1035**; (2) at least one input device **1030** (which may include contact and/or non-contact interfaces); (3) at least one transponder **1054**; (4) at least one wireless communication component **1056**; (5) at least one wired/wireless power distribution component **1058**; (6) at least one sensor **1060**; (7) at least one data preservation component **1062**; (8) at least one motion/gesture analysis and interpretation component **1064**; (9) at least one motion detection component **1066**; (10) at least one portable power source **1068**; (11) at least one geolocation module **1076**; (12) at least one user identification module **1077**; (13) at least one user/device tracking module **1078**; and (14) at least one information filtering module **1079**.

The at least one output device **1020** includes at least one display device **1035** configured to display any game(s) displayed by the EGM and any suitable information associated with such game(s). In certain embodiments, the display devices are connected to or mounted on a housing of the EGM (described below). In various embodiments, the display devices serve as digital glass configured to advertise certain games or other aspects of the gaming establishment in which the EGM is located. In various embodiments, the EGM includes one or more of the following display devices: (a) a central display device; (b) a player tracking display configured to display various information regarding a user's player tracking status (as described below); (c) a secondary or upper display device in addition to the central display device and the player tracking display; (d) a credit display configured to display a current quantity of credits, amount of cash, account balance, or the equivalent; and (e) a bet

display configured to display an amount wagered for one or more plays of one or more games. The example EGM 2000a illustrated in FIG. 10A includes a central display device 2116, a player tracking display 2140, a credit display 2120, and a bet display 2122. The example EGM 2000b illustrated in FIG. 10B includes a central display device 2116, an upper display device 2118, a player tracking display 2140, a credit display 2120, and a bet display 2122.

In various embodiments, the display devices include, without limitation: a monitor, a television display, a plasma display, a liquid crystal display (LCD), a display based on light emitting diodes (LEDs), a display based on a plurality of organic light-emitting diodes (OLEDs), a display based on polymer light-emitting diodes (PLEDs), a display based on a plurality of surface-conduction electron-emitters (SEDs), a display including a projected and/or reflected image, or any other suitable electronic device or display mechanism. In certain embodiments, as described above, the display device includes a touchscreen with an associated touch-screen controller. The display devices may be of any suitable sizes, shapes, and configurations.

The display devices of the EGM are configured to display one or more game and/or non-game images, symbols, and indicia. In certain embodiments, the display devices of the EGM are configured to display any suitable visual representation or exhibition of the movement of objects; dynamic lighting; video images; images of people, characters, places, things, and faces of cards; and the like. In certain embodiments, the display devices of the EGM are configured to display one or more video reels, one or more video wheels, and/or one or more video dice. In other embodiments, certain of the displayed images, symbols, and indicia are in mechanical form. That is, in these embodiments, the display device includes any electromechanical device, such as one or more rotatable wheels, one or more reels, and/or one or more dice, configured to display at least one or a plurality of game or other suitable images, symbols, or indicia.

In various embodiments, the at least one output device 1020 includes a payout device. In these embodiments, after the EGM receives an actuation of a cashout device (described below), the EGM causes the payout device to provide a payment to the user. In one embodiment, the payout device is one or more of: (a) a ticket printer and dispenser configured to print and dispense a ticket or credit slip associated with a monetary value, wherein the ticket or credit slip may be redeemed for its monetary value via a cashier, a kiosk, or other suitable redemption system; (b) a bill dispenser configured to dispense paper currency; (c) a coin dispenser configured to dispense coins or tokens (such as into a coin payout tray); and (d) any suitable combination thereof. The example EGMs 2000a and 2000b illustrated in FIGS. 10A and 10B each include a ticket printer and dispenser 2136.

In certain embodiments, rather than dispensing bills, coins, or a physical ticket having a monetary value to the user following receipt of an actuation of the cashout device, the payout device is configured to cause a payment to be provided to the user in the form of an electronic funds transfer, such as via a direct deposit into a bank account, a casino account, or a prepaid account of the user; via a transfer of funds onto an electronically recordable identification card or smart card of the user; or via sending a virtual ticket having a monetary value to an electronic device of the user.

While any credit balances, any wagers, any values, and any awards are described herein as amounts of monetary credits or currency, one or more of such credit balances, such

wagers, such values, and such awards may be for non-monetary credits, promotional credits, of player tracking points or credits.

In certain embodiments, the at least one output device 1020 is a sound generating device controlled by one or more sound cards. In one such embodiment, the sound generating device includes one or more speakers or other sound generating hardware and/or software configured to generate sounds, such as by playing music for any games or by playing music for other modes of the EGM, such as an attract mode. The example EGMs 2000a and 2000b illustrated in FIGS. 10A and 10B each include a plurality of speakers 2150. In another such embodiment, the EGM provides dynamic sounds coupled with attractive multimedia images displayed on one or more of the display devices to provide an audio-visual representation or to otherwise display full-motion video with sound to attract users to the EGM. In certain embodiments, the EGM displays a sequence of audio and/or visual attraction messages during idle periods to attract potential users to the EGM. The videos may be customized to provide any appropriate information.

The at least one input device 1030 may include any suitable device that enables an input signal to be produced and received by the at least one processor 1010 of the EGM.

In one embodiment, the at least one input device 1030 includes a payment device configured to communicate with the at least one processor of the EGM to fund the EGM. In certain embodiments, the payment device includes one or more of: (a) a bill acceptor into which paper money is inserted to fund the EGM; (b) a ticket acceptor into which a ticket or a voucher is inserted to fund the EGM; (c) a coin slot into which coins or tokens are inserted to fund the EGM; (d) a reader or a validator for credit cards, debit cards, or credit slips into which a credit card, debit card, or credit slip is inserted to fund the EGM; (e) a user identification card reader into which a user identification card is inserted to fund the EGM; or (f) any suitable combination thereof. The example EGMs 2000a and 2000b illustrated in FIGS. 10A and 10B each include a combined bill and ticket acceptor 2128 and a coin slot 2126.

In one embodiment, the at least one input device 1030 includes a payment device configured to enable the EGM to be funded via an electronic funds transfer, such as a transfer of funds from a bank account. In another embodiment, the EGM includes a payment device configured to communicate with a mobile device of a user, such as a mobile phone, a radio frequency identification tag, or any other suitable wired or wireless device, to retrieve relevant information associated with that user to fund the EGM. When the EGM is funded, the at least one processor determines the amount of funds entered and displays the corresponding amount on a credit display or any other suitable display as described below.

In certain embodiments, the at least one input device 1030 includes at least one wagering or betting device. In various embodiments, the one or more wagering or betting devices are each: (1) a mechanical button supported by the housing of the EGM (such as a hard key or a programmable soft key), or (2) an icon displayed on a display device of the EGM (described below) that is actuatable via a touch screen of the EGM (described below) or via use of a suitable input device of the EGM (such as a mouse or a joystick). One such wagering or betting device is as a maximum wager or bet device that, when actuated, causes the EGM to place a maximum wager on a play of a game. Another such wagering or betting device is a repeat bet device that, when actuated, causes the EGM to place a wager that is equal to

the previously placed wager on a play of a game. A further such wagering or betting device is a bet one device that, when actuated, causes the EGM to increase the wager by one credit. Generally, upon actuation of one of the wagering or betting devices, the quantity of credits displayed in a credit meter (described below) decreases by the amount of credits wagered, while the quantity of credits displayed in a bet display (described below) increases by the amount of credits wagered.

In various embodiments, the at least one input device **1030** includes at least one game play activation device. In various embodiments, the one or more game play initiation devices are each: (1) a mechanical button supported by the housing of the EGM (such as a hard key or a programmable soft key), or (2) an icon displayed on a display device of the EGM (described below) that is actuatable via a touch screen of the EGM (described below) or via use of a suitable input device of the EGM (such as a mouse or a joystick). After a user appropriately funds the EGM and places a wager, the EGM activates the game play activation device to enable the user to actuate the game play activation device to initiate a play of a game on the EGM (or another suitable sequence of events associated with the EGM). After the EGM receives an actuation of the game play activation device, the EGM initiates the play of the game. The example EGMs **2000a** and **2000b** illustrated in FIGS. **10A** and **10B** each include a game play activation device in the form of a game play initiation button **2132**. In other embodiments, the EGM begins game play automatically upon appropriate funding rather than upon utilization of the game play activation device.

In other embodiments, the at least one input device **1030** includes a cashout device. In various embodiments, the cashout device is: (1) a mechanical button supported by the housing of the EGM (such as a hard key or a programmable soft key), or (2) an icon displayed on a display device of the EGM (described below) that is actuatable via a touch screen of the EGM (described below) or via use of a suitable input device of the EGM (such as a mouse or a joystick). When the EGM receives an actuation of the cashout device from a user and the user has a positive (i.e., greater-than-zero) credit balance, the EGM initiates a payout associated with the user's credit balance. The example EGMs **2000a** and **2000b** illustrated in FIGS. **10A** and **10B** each include a cashout device in the form of a cashout button **2134**.

In various embodiments, the at least one input device **1030** includes a plurality of buttons that are programmable by the EGM operator to, when actuated, cause the EGM to perform particular functions. For instance, such buttons may be hard keys, programmable soft keys, or icons icon displayed on a display device of the EGM (described below) that are actuatable via a touch screen of the EGM (described below) or via use of a suitable input device of the EGM (such as a mouse or a joystick). The example EGMs **2000a** and **2000b** illustrated in FIGS. **10A** and **10B** each include a plurality of such buttons **2130**.

In certain embodiments, the at least one input device **1030** includes a touchscreen coupled to a touch-screen controller or other touch-sensitive display overlay to enable interaction with any images displayed on a display device (as described below). One such input device is a conventional touch-screen button panel. The touchscreen and the touch-screen controller are connected to a video controller. In these embodiments, signals are input to the EGM by touching the touch screen at the appropriate locations.

In embodiments including a player tracking system, as further described below, the at least one input device **1030**

includes a card reader in communication with the at least one processor of the EGM. The example EGMs **2000a** and **2000b** illustrated in FIGS. **10A** and **10B** each include a card reader **2138**. The card reader is configured to read a user identification card inserted into the card reader.

The at least one wireless communication component **1056** includes one or more communication interfaces having different architectures and utilizing a variety of protocols, such as (but not limited to) 802.11 (WiFi); 802.15 (including Bluetooth™); 802.16 (WiMax); 802.22; cellular standards such as CDMA, CDMA2000, and WCDMA; Radio Frequency (e.g., RFID); infrared; and Near Field Magnetic communication protocols. The at least one wireless communication component **1056** transmits electrical, electromagnetic, or optical signals that carry digital data streams or analog signals representing various types of information.

The at least one wired/wireless power distribution component **1058** includes components or devices that are configured to provide power to other devices. For example, in one embodiment, the at least one power distribution component **1058** includes a magnetic induction system that is configured to provide wireless power to one or more user input devices near the EGM. In one embodiment, a user input device docking region is provided, and includes a power distribution component that is configured to recharge a user input device without requiring metal-to-metal contact. In one embodiment, the at least one power distribution component **1058** is configured to distribute power to one or more internal components of the EGM, such as one or more rechargeable power sources (e.g., rechargeable batteries) located at the EGM.

In certain embodiments, the at least one sensor **1060** includes at least one of: optical sensors, pressure sensors, RF sensors, infrared sensors, image sensors, thermal sensors, and biometric sensors. The at least one sensor **1060** may be used for a variety of functions, such as: detecting movements and/or gestures of various objects within a predetermined proximity to the EGM; detecting the presence and/or identity of various persons (e.g., users, casino employees, etc.), devices (e.g., user input devices), and/or systems within a predetermined proximity to the EGM.

The at least one data preservation component **1062** is configured to detect or sense one or more events and/or conditions that, for example, may result in damage to the EGM and/or that may result in loss of information associated with the EGM. Additionally, the data preservation system **1062** may be operable to initiate one or more appropriate action(s) in response to the detection of such events/conditions.

The at least one motion/gesture analysis and interpretation component **1064** is configured to analyze and/or interpret information relating to detected user movements and/or gestures to determine appropriate user input information relating to the detected user movements and/or gestures. For example, in one embodiment, the at least one motion/gesture analysis and interpretation component **1064** is configured to perform one or more of the following functions: analyze the detected gross motion or gestures of a user; interpret the user's motion or gestures (e.g., in the context of a casino game being played) to identify instructions or input from the user; utilize the interpreted instructions/input to advance the game state; etc. In other embodiments, at least a portion of these additional functions may be implemented at a remote system or device.

The at least one portable power source **1068** enables the EGM to operate in a mobile environment. For example, in one embodiment, the EGM **300** includes one or more rechargeable batteries.

The at least one geolocation module **1076** is configured to acquire geolocation information from one or more remote sources and use the acquired geolocation information to determine information relating to a relative and/or absolute position of the EGM. For example, in one implementation, the at least one geolocation module **1076** is configured to receive GPS signal information for use in determining the position or location of the EGM. In another implementation, the at least one geolocation module **1076** is configured to receive multiple wireless signals from multiple remote devices (e.g., EGMs, servers, wireless access points, etc.) and use the signal information to compute position/location information relating to the position or location of the EGM.

The at least one user identification module **1077** is configured to determine the identity of the current user or current owner of the EGM. For example, in one embodiment, the current user is required to perform a login process at the EGM in order to access one or more features. Alternatively, the EGM is configured to automatically determine the identity of the current user based on one or more external signals, such as an RFID tag or badge worn by the current user and that provides a wireless signal to the EGM that is used to determine the identity of the current user. In at least one embodiment, various security features are incorporated into the EGM to prevent unauthorized users from accessing confidential or sensitive information.

The at least one information filtering module **1079** is configured to perform filtering (e.g., based on specified criteria) of selected information to be displayed at one or more displays **1035** of the EGM.

In various embodiments, the EGM includes a plurality of communication ports configured to enable the at least one processor of the EGM to communicate with and to operate with external peripherals, such as: accelerometers, arcade sticks, bar code readers, bill validators, biometric input devices, bonus devices, button panels, card readers, coin dispensers, coin hoppers, display screens or other displays or video sources, expansion buses, information panels, keypads, lights, mass storage devices, microphones, motion sensors, motors, printers, reels, SCSI ports, solenoids, speakers, thumbsticks, ticket readers, touch screens, trackballs, touchpads, wheels, and wireless communication devices.

As generally described above, in certain embodiments, such as the example EGMs **2000a** and **2000b** illustrated in FIGS. **10A** and **10B**, the EGM has a support structure, housing, or cabinet that provides support for a plurality of the input devices and the output devices of the EGM. Further, the EGM is configured such that a user may operate it while standing or sitting. In various embodiments, the EGM is positioned on a base or stand, or is configured as a pub-style tabletop game (not shown) that a user may operate typically while sitting. As illustrated by the different example EGMs **2000a** and **2000b** shown in FIGS. **10A** and **10B**, EGMs may have varying housing and display configurations.

In certain embodiments, the EGM is a device that has obtained approval from a regulatory gaming commission, and in other embodiments, the EGM is a device that has not obtained approval from a regulatory gaming commission.

The EGMs described above are merely three examples of different types of EGMs. Certain of these example EGMs may include one or more elements that may not be included

in all gaming systems, and these example EGMs may not include one or more elements that are included in other gaming systems. For example, certain EGMs include a coin acceptor while others do not.

5 In various embodiments, an EGM may be implemented in one of a variety of different configurations. In various embodiments, the EGM may be implemented as one of: (a) a dedicated EGM in which computerized game programs executable by the EGM for controlling any primary or base 10 games (referred to herein as "primary games") and/or any secondary or bonus games or other functions (referred to herein as "secondary games") displayed by the EGM are provided with the EGM before delivery to a gaming establishment or before being provided to a user; and (b) a 15 changeable EGM in which computerized game programs executable by the EGM for controlling any primary games and/or secondary games displayed by the EGM are downloadable or otherwise transferred to the EGM through a data network or remote communication link; from a USB drive, 20 flash memory card, or other suitable memory device; or in any other suitable manner after the EGM is physically located in a gaming establishment or after the EGM is provided to a user.

As generally explained above, in various embodiments in 25 which the gaming system includes a server and a changeable EGM, the at least one memory device of the server stores different game programs and instructions executable by the at least one processor of the changeable EGM to control one or more primary games and/or secondary games displayed 30 by the changeable EGM. More specifically, each such executable game program represents a different game or a different type of game that the at least one changeable EGM is configured to operate. In one example, certain of the game programs are executable by the changeable EGM to operate 35 games having the same or substantially the same game play but different paytables. In different embodiments, each executable game program is associated with a primary game, a secondary game, or both. In certain embodiments, an executable game program is executable by the at least one 40 processor of the at least one changeable EGM as a secondary game to be played simultaneously with a play of a primary game (which may be downloaded to or otherwise stored on the at least one changeable EGM), or vice versa.

In operation of such embodiments, the server is configured 45 to communicate one or more of the stored executable game programs to the at least one processor of the changeable EGM. In different embodiments, a stored executable game program is communicated or delivered to the at least one processor of the changeable EGM by: (a) embedding the executable game program in a device or a component (such as a microchip to be inserted into the changeable EGM); (b) writing the executable game program onto a disc or other media; or (c) uploading or streaming the executable game 50 program over a data network (such as a dedicated data network). After the executable game program is communicated from the server to the changeable EGM, the at least one processor of the changeable EGM executes the executable game program to enable the primary game and/or the secondary game associated with that executable game program 55 to be played using the display device(s) and/or the input device(s) of the changeable EGM. That is, when an executable game program is communicated to the at least one processor of the changeable EGM, the at least one processor of the changeable EGM changes the game or the 60 type of game that may be played using the changeable EGM.

In certain embodiments, the gaming system randomly determines any game outcome(s) (such as a win outcome)

and/or award(s) (such as a quantity of credits to award for the win outcome) for a play of a primary game and/or a play of a secondary game based on probability data. In certain such embodiments, this random determination is provided through utilization of an RNG, such as a true RNG or a pseudo RNG, or any other suitable randomization process. In one such embodiment, each game outcome or award is associated with a probability, and the gaming system generates the game outcome(s) and/or the award(s) to be provided based on the associated probabilities. In these embodiments, since the gaming system generates game outcomes and/or awards randomly or based on one or more probability calculations, there is no certainty that the gaming system will ever provide any specific game outcome and/or award.

In certain embodiments, the gaming system maintains one or more predetermined pools or sets of predetermined game outcomes and/or awards. In certain such embodiments, upon generation or receipt of a game outcome and/or award request, the gaming system independently selects one of the predetermined game outcomes and/or awards from the one or more pools or sets. The gaming system flags or marks the selected game outcome and/or award as used. Once a game outcome or an award is flagged as used, it is prevented from further selection from its respective pool or set; that is, the gaming system does not select that game outcome or award upon another game outcome and/or award request. The gaming system provides the selected game outcome and/or award.

In certain embodiments, the gaming system determines a predetermined game outcome and/or award based on the results of a bingo, keno, or lottery game. In certain such embodiments, the gaming system utilizes one or more bingo, keno, or lottery games to determine the predetermined game outcome and/or award provided for a primary game and/or a secondary game. The gaming system is provided or associated with a bingo card. Each bingo card consists of a matrix or array of elements, wherein each element is designated with separate indicia. After a bingo card is provided, the gaming system randomly selects or draws a plurality of the elements. As each element is selected, a determination is made as to whether the selected element is present on the bingo card. If the selected element is present on the bingo card, that selected element on the provided bingo card is marked or flagged. This process of selecting elements and marking any selected elements on the provided bingo cards continues until one or more predetermined patterns are marked on one or more of the provided bingo cards. After one or more predetermined patterns are marked on one or more of the provided bingo cards, game outcome and/or award is determined based, at least in part, on the selected elements on the provided bingo cards.

In certain embodiments in which the gaming system includes a server and an EGM, the EGM is configured to communicate with the server for monitoring purposes only. In such embodiments, the EGM determines the game outcome(s) and/or award(s) to be provided in any of the manners described above, and the server monitors the activities and events occurring on the EGM. In one such embodiment, the gaming system includes a real-time or online accounting and gaming information system configured to communicate with the server. In this embodiment, the accounting and gaming information system includes: (a) a user database configured to store user profiles, (b) a player tracking module configured to track users (as described below), and (c) a credit system configured to provide automated transactions.

As noted above, in various embodiments, the gaming system includes one or more executable game programs executable by at least one processor of the gaming system to provide one or more primary games and one or more secondary games. The primary game(s) and the secondary game(s) may comprise any suitable games and/or wagering games, such as, but not limited to electro-mechanical or video slot or spinning reel type games; video card games such as video draw poker, multi-hand video draw poker, other video poker games, video blackjack games, and video baccarat games; video keno games; video bingo games; and video selection games.

In certain embodiments in which the primary game is a slot or spinning reel type game, the gaming system includes one or more reels in either an electromechanical form with mechanical rotating reels or in a video form with simulated reels and movement thereof. Each reel displays a plurality of indicia or symbols, such as bells, hearts, fruits, numbers, letters, bars, or other images that typically correspond to a theme associated with the gaming system. In certain such embodiments, the gaming system includes one or more paylines associated with the reels. The example EGM 2000b shown in FIG. 10B includes a payline 1152 and a plurality of reels 1154. In certain embodiments, one or more of the reels are independent reels or unisymbol reels. In such embodiments, each independent reel generates and displays one symbol.

In various embodiments, one or more of the paylines is horizontal, vertical, circular, diagonal, angled, or any suitable combination thereof. In other embodiments, each of one or more of the paylines is associated with a plurality of adjacent symbol display areas on a requisite number of adjacent reels. In one such embodiment, one or more paylines are formed between at least two symbol display areas that are adjacent to each other by either sharing a common side or sharing a common corner (i.e., such paylines are connected paylines). The gaming system enables a wager to be placed on one or more of such paylines to activate such paylines. In other embodiments in which one or more paylines are formed between at least two adjacent symbol display areas, the gaming system enables a wager to be placed on a plurality of symbol display areas, which activates those symbol display areas.

In various embodiments, the gaming system provides one or more awards after a spin of the reels when specified types and/or configurations of the indicia or symbols on the reels occur on an active payline or otherwise occur in a winning pattern, occur on the requisite number of adjacent reels, and/or occur in a scatter pay arrangement.

In certain embodiments, the gaming system employs a ways to win award determination. In these embodiments, any outcome to be provided is determined based on a number of associated symbols that are generated in active symbol display areas on the requisite number of adjacent reels (i.e., not on paylines passing through any displayed winning symbol combinations). If a winning symbol combination is generated on the reels, one award for that occurrence of the generated winning symbol combination is provided.

In various embodiments, the gaming system includes a progressive award. Typically, a progressive award includes an initial amount and an additional amount funded through a portion of each wager placed to initiate a play of a primary game. When one or more triggering events occurs, the gaming system provides at least a portion of the progressive award. After the gaming system provides the progressive award, an amount of the progressive award is reset to the

initial amount and a portion of each subsequent wager is allocated to the next progressive award.

As generally noted above, in addition to providing winning credits or other awards for one or more plays of the primary game(s), in various embodiments the gaming system provides credits or other awards for one or more plays of one or more secondary games. The secondary game typically enables an award to be obtained addition to any award obtained through play of the primary game(s). The secondary game(s) typically produces a higher level of user excitement than the primary game(s) because the secondary game(s) provides a greater expectation of winning than the primary game(s) and is accompanied with more attractive or unusual features than the primary game(s). The secondary game(s) may be any type of suitable game, either similar to or completely different from the primary game.

In various embodiments, the gaming system automatically provides or initiates the secondary game upon the occurrence of a triggering event or the satisfaction of a qualifying condition. In other embodiments, the gaming system initiates the secondary game upon the occurrence of the triggering event or the satisfaction of the qualifying condition and upon receipt of an initiation input. In certain embodiments, the triggering event or qualifying condition is a selected outcome in the primary game(s) or a particular arrangement of one or more indicia on a display device for a play of the primary game(s), such as a "BONUS" symbol appearing on three adjacent reels along a payline following a spin of the reels for a play of the primary game. In other embodiments, the triggering event or qualifying condition occurs based on a certain amount of game play (such as number of games, number of credits, amount of time) being exceeded, or based on a specified number of points being earned during game play. Any suitable triggering event or qualifying condition or any suitable combination of a plurality of different triggering events or qualifying conditions may be employed.

In other embodiments, at least one processor of the gaming system randomly determines when to provide one or more plays of one or more secondary games. In one such embodiment, no apparent reason is provided for providing the secondary game. In this embodiment, qualifying for a secondary game is not triggered by the occurrence of an event in any primary game or based specifically on any of the plays of any primary game. That is, qualification is provided without any explanation or, alternatively, with a simple explanation. In another such embodiment, the gaming system determines qualification for a secondary game at least partially based on a game triggered or symbol triggered event, such as at least partially based on play of a primary game.

In various embodiments, after qualification for a secondary game has been determined, the secondary game participation may be enhanced through continued play on the primary game. Thus, in certain embodiments, for each secondary game qualifying event, such as a secondary game symbol, that is obtained, a given number of secondary game wagering points or credits is accumulated in a "secondary game meter" configured to accrue the secondary game wagering credits or entries toward eventual participation in the secondary game. In one such embodiment, the occurrence of multiple such secondary game qualifying events in the primary game results in an arithmetic or exponential increase in the number of secondary game wagering credits awarded. In another such embodiment, any extra secondary game wagering credits may be redeemed during the secondary game to extend play of the secondary game.

In certain embodiments, no separate entry fee or buy-in for the secondary game is required. That is, entry into the secondary game cannot be purchased, rather, in these embodiments entry must be won or earned through play of the primary game, thereby encouraging play of the primary game. In other embodiments, qualification for the secondary game is accomplished through a simple "buy-in." For example, qualification through other specified activities is unsuccessful, payment of a fee or placement of an additional wager "buys-in" to the secondary game. In certain embodiments, a separate side wager must be placed on the secondary game, or a wager of a designated amount must be placed on the primary game to enable qualification for the secondary game. In these embodiments, the secondary game triggering event must occur and the side wager (or designated primary game wager amount) must have been placed for the secondary game to trigger.

In various embodiments in which the gaming system includes a plurality of EGMs, the EGMs are configured to communicate with one another to provide a group gaming environment. In certain such embodiments, the EGMs enable users of those EGMs to work in conjunction with one another, such as by enabling the users to play together as a team or group, to win one or more awards. In other such embodiments, the EGMs enable users of those EGMs to compete against one another for one or more awards. In one such embodiment, the EGMs enable the users of those EGMs to participate in one or more gaming tournaments for one or more awards.

In various embodiments, the gaming system includes one or more player tracking systems. Such player tracking systems enable operators of the gaming system (such as casinos or other gaming establishments) to recognize the value of customer loyalty by identifying frequent customers and rewarding them for their patronage. Such a player tracking system is configured to track a user's gaming activity. In one such embodiment, the player tracking system does so through the use of player tracking cards. In this embodiment, a user is issued a user identification card that has an encoded user identification number that uniquely identifies the user. When the user's playing tracking card is inserted into a card reader of the gaming system to begin a gaming session, the card reader reads the user identification number off the player tracking card to identify the user. The gaming system timely tracks any suitable information or data relating to the identified user's gaming session. The gaming system also timely tracks when the player tracking card is removed to conclude play for that gaming session. In another embodiment, rather than requiring insertion of a player tracking card into the card reader, the gaming system utilizes one or more portable devices, such as a mobile phone, a radio frequency identification tag, or any other suitable wireless device, to track when a gaming session begins and ends. In another embodiment, the gaming system utilizes any suitable biometric technology or ticket technology to track when a gaming session begins and ends.

In such embodiments, during one or more gaming sessions, the gaming system tracks any suitable information or data, such as any amounts wagered, average wager amounts, and/or the time at which these wagers are placed. In different embodiments, for one or more users, the player tracking system includes the user's account number, the user's card number, the user's first name, the user's surname, the user's preferred name, the user's player tracking ranking, any promotion status associated with the user's player tracking card, the user's address, the user's birthday, the user's anniversary, the user's recent gaming sessions, or any other

suitable data. In various embodiments, such tracked information and/or any suitable feature associated with the player tracking system is displayed on a player tracking display. In various embodiments, such tracked information and/or any suitable feature associated with the player tracking system is displayed via one or more service windows that are displayed on the central display device and/or the upper display device.

In various embodiments, the gaming system includes one or more servers configured to communicate with a personal gaming device—such as a smartphone, a tablet computer, a desktop computer, or a laptop computer—to enable web-based game play using the personal gaming device. In various embodiments, the user must first access a gaming website via an Internet browser of the personal gaming device or execute an application (commonly called an “app”) installed on the personal gaming device before the user can use the personal gaming device to participate in web-based game play. In certain embodiments, the one or more servers and the personal gaming device operate in a thin-client environment. In these embodiments, the personal gaming device receives inputs via one or more input devices (such as a touch screen and/or physical buttons), the personal gaming device sends the received inputs to the one or more servers, the one or more servers make various determinations based on the inputs and determine content to be displayed (such as a randomly determined game outcome and corresponding award), the one or more servers send the content to the personal gaming device, and the personal gaming device displays the content.

In certain such embodiments, the one or more servers must identify the user before enabling game play on the personal gaming device (or, in some embodiments, before enabling monetary wager-based game play on the personal gaming device). In these embodiments, the user must identify herself to the one or more servers, such as by inputting the user's unique username and password combination, providing an input to a biometric sensor (e.g., a fingerprint sensor, a retinal sensor, a voice sensor, or a facial-recognition sensor), or providing any other suitable information.

Once identified, the one or more servers enable the user to establish an account balance from which the user can draw credits usable to wager on plays of a game. In certain embodiments, the one or more servers enable the user to initiate an electronic funds transfer to transfer funds from a bank account to the user's account balance. In other embodiments, the one or more servers enable the user to make a payment using the user's credit card, debit card, or other suitable device to add money to the user's account balance. In other embodiments, the one or more servers enable the user to add money to the user's account balance via a peer-to-peer type application, such as PayPal or Venmo. The one or more servers also enable the user to cash out the user's account balance (or part of it) in any suitable manner, such as via an electronic funds transfer, by initiating creation of a paper check that is mailed to the user, or by initiating printing of a voucher at a kiosk in a gaming establishment.

In certain embodiments, the one or more servers include a payment server that handles establishing and cashing out users' account balances and a separate game server configured to determine the outcome and any associated award for a play of a game. In these embodiments, the game server is configured to communicate with the personal gaming device and the payment device, and the personal gaming device and the payment device are not configured to directly communicate with one another. In these embodiments, when the game server receives data representing a request to start a

play of a game at a desired wager, the game server sends data representing the desired wager to the payment server. The payment server determines whether the user's account balance can cover the desired wager (i.e., includes a monetary balance at least equal to the desired wager).

If the payment server determines that the user's account balance cannot cover the desired wager, the payment server notifies the game server, which then instructs the personal gaming device to display a suitable notification to the user that the user's account balance is too low to place the desired wager. If the payment server determines that the user's account balance can cover the desired wager, the payment server deducts the desired wager from the account balance and notifies the game server. The game server then determines an outcome and any associated award for the play of the game. The game server notifies the payment server of any nonzero award, and the payment server increases the user's account balance by the nonzero award. The game server sends data representing the outcome and any award to the personal gaming device, which displays the outcome and any award.

In certain embodiments, the one or more servers enable web-based game play using a personal gaming device only if the personal gaming device satisfies one or more jurisdictional requirements. In one embodiment, the one or more servers enable web-based game play using the personal gaming device only if the personal gaming device is located within a designated geographic area (such as within certain state or county lines or within the boundaries of a gaming establishment). In this embodiment, the geolocation module of the personal gaming device determines the location of the personal gaming device and sends the location to the one or more servers, which determine whether the personal gaming device is located within the designated geographic area. In various embodiments, the one or more servers enable non-monetary wager-based game play if the personal gaming device is located outside of the designated geographic area.

In various embodiments, the gaming system includes an EGM configured to communicate with a personal gaming device—such as a smartphone, a tablet computer, a desktop computer, or a laptop computer—to enable tethered mobile game play using the personal gaming device. Generally, in these embodiments, the EGM establishes communication with the personal gaming device and enables the user to play games on the EGM remotely via the personal gaming device. In certain embodiments, the gaming system includes a geo-fence system that enables tethered game play within a particular geographic area but not outside of that geographic area.

In certain embodiments, the gaming system is configured to communicate with a social network server that hosts or partially hosts a social networking website via a data network (such as the Internet) to integrate a user's gaming experience with the user's social networking account. This enables the gaming system to send certain information to the social network server that the social network server can use to create content (such as text, an image, and/or a video) and post it to the user's wall, newsfeed, or similar area of the social networking website accessible by the user's connections (and in certain cases the public) such that the user's connections can view that information. This also enables the gaming system to receive certain information from the social network server, such as the user's likes or dislikes or the user's list of connections. In certain embodiments, the gaming system enables the user to link the user's user account to the user's social networking account(s). This enables the gaming system to, once it identifies the user and

initiates a gaming session (such as via the user logging in to a website (or an application) on the user's personal gaming device or via the user inserting the user's player tracking card into an EGM), link that gaming session to the user's social networking account(s). In other embodiments, the gaming system enables the user to link the user's social networking account(s) to individual gaming sessions when desired by providing the required login information.

For instance, in one embodiment, if a user wins a particular award (e.g., a progressive award or a jackpot award) or an award that exceeds a certain threshold (e.g., an award exceeding \$1,000), the gaming system sends information about the award to the social network server to enable the server to create associated content (such as a screenshot of the outcome and associated award) and to post that content to the user's wall (or other suitable area) of the social networking website for the user's connections to see (and to entice them to play). In another embodiment, if a user joins a multiuser game and there is another seat available, the gaming system sends that information to the social network sever to enable the server to create associated content (such as text indicating a vacancy for that particular game) and to post that content to the user's wall (or other suitable area) of the social networking website for the user's connections to see (and to entice them to fill the vacancy). In another embodiment, if the user consents, the gaming system sends advertisement information or offer information to the social network server to enable the social network server to create associated content (such as text or an image reflecting an advertisement and/or an offer) and to post that content to the user's wall (or other suitable area) of the social networking website for the user's connections to see. In another embodiment, the gaming system enables the user to recommend a game to the user's connections by posting a recommendation to the user's wall (or other suitable area) of the social networking website.

Certain of the gaming systems described herein, such as EGMs located in a casino or another gaming establishment, include certain components and/or are configured to operate in certain manners that differentiate these systems from general purpose computing devices, i.e., certain personal gaming devices such as desktop computers and laptop computers.

For instance, EGMs are highly regulated to ensure fairness, and, in many cases, EGMs are configured to award monetary awards up to multiple millions of dollars. To satisfy security and regulatory requirements in a gaming environment, hardware and/or software architectures are implemented in EGMs that differ significantly from those of general purpose computing devices. For purposes of illustration, a description of EGMs relative to general purpose computing devices and some examples of these additional (or different) hardware and/or software architectures found in EGMs are described below.

At first glance, one might think that adapting general purpose computing device technologies to the gaming industry and EGMs would be a simple proposition because both general purpose computing devices and EGMs employ processors that control a variety of devices. However, due to at least: (1) the regulatory requirements placed on EGMs, (2) the harsh environment in which EGMs operate, (3) security requirements, and (4) fault tolerance requirements, adapting general purpose computing device technologies to EGMs can be quite difficult. Further, techniques and methods for solving a problem in the general purpose computing device industry, such as device compatibility and connectivity issues, might not be adequate in the gaming industry. For

instance, a fault or a weakness tolerated in a general purpose computing device, such as security holes in software or frequent crashes, is not tolerated in an EGM because in an EGM these faults can lead to a direct loss of funds from the EGM, such as stolen cash or loss of revenue when the EGM is not operating properly or when the random outcome determination is manipulated.

Certain differences between general purpose computing devices and EGMs are described below. A first difference 10 between EGMs and general purpose computing devices is that EGMs are state-based systems. A state-based system stores and maintains its current state in a non-volatile memory such that, in the event of a power failure or other malfunction, the state-based system can return to that state 15 when the power is restored, or the malfunction is remedied. For instance, for a state-based EGM, if the EGM displays an award for a game of chance but the power to the EGM fails before the EGM provides the award to the user, the EGM stores the pre-power failure state in a non-volatile memory, 20 returns to that state upon restoration of power, and provides the award to the user. This requirement affects the software and hardware design on EGMs. General purpose computing devices are not state-based machines, and a majority of data 25 is usually lost when a malfunction occurs on a general purpose computing device.

A second difference between EGMs and general purpose computing devices is that, for regulatory purposes, the software on the EGM utilized to operate the EGM has been 30 designed to be static and monolithic to prevent cheating by the operator of the EGM. For instance, one solution that has been employed in the gaming industry to prevent cheating and to satisfy regulatory requirements has been to manufacture an EGM that can use a proprietary processor running 35 instructions to provide the game of chance from an EPROM or other form of non-volatile memory. The coding instructions on the EPROM are static (non-changeable) and must be approved by a gaming regulators in a particular jurisdiction and installed in the presence of a person representing the gaming jurisdiction. Any changes to any part of the software 40 required to generate the game of chance, such as adding a new device driver used to operate a device during generation of the game of chance, can require burning a new EPROM approved by the gaming jurisdiction and reinstalling the new EPROM on the EGM in the presence of a gaming regulator. 45 Regardless of whether the EPROM solution is used, to gain approval in most gaming jurisdictions, an EGM must demonstrate sufficient safeguards that prevent an operator or a user of an EGM from manipulating the EGM's hardware and software in a manner that gives him an unfair, and in 50 some cases illegal, advantage.

A third difference between EGMs and general purpose computing devices is authentication—EGMs storing code are 55 configured to authenticate the code to determine if the code is unaltered before executing the code. If the code has been altered, the EGM prevents the code from being executed. The code authentication requirements in the gaming industry affect both hardware and software designs on EGMs. Certain EGMs use hash functions to authenticate 60 code. For instance, one EGM stores game program code, a hash function, and an authentication hash (which may be encrypted). Before executing the game program code, the EGM hashes the game program code using the hash function to obtain a result hash and compares the result hash to the authentication hash. If the result hash matches the authentication hash, the EGM determines that the game program code is valid and executes the game program code. If the result hash does not match the authentication hash, the EGM

determines that the game program code has been altered (i.e., may have been tampered with) and prevents execution of the game program code.

A fourth difference between EGMs and general purpose computing devices is that EGMs have unique peripheral device requirements that differ from those of a general purpose computing device, such as peripheral device security requirements not usually addressed by general purpose computing devices. For instance, monetary devices, such as coin dispensers, bill validators, and ticket printers and computing devices that are used to govern the input and output of cash or other items having monetary value (such as tickets) to and from an EGM have security requirements that are not typically addressed in general purpose computing devices. Therefore, many general purpose computing device techniques and methods developed to facilitate device connectivity and device compatibility do not address the emphasis placed on security in the gaming industry.

To address some of the issues described above, a number of hardware/software components and architectures are utilized in EGMs that are not typically found in general purpose computing devices. These hardware/software components and architectures, as described below in more detail, include but are not limited to watchdog timers, voltage monitoring systems, state-based software architecture and supporting hardware, specialized communication interfaces, security monitoring, and trusted memory.

Certain EGMs use a watchdog timer to provide a software failure detection mechanism. In a normally operating EGM, the operating software periodically accesses control registers in the watchdog timer subsystem to "re-trigger" the watchdog. Should the operating software fail to access the control registers within a preset timeframe, the watchdog timer will timeout and generate a system reset. Typical watchdog timer circuits include a loadable timeout counter register to enable the operating software to set the timeout interval within a certain range of time. A differentiating feature of some circuits is that the operating software cannot completely disable the function of the watchdog timer. In other words, the watchdog timer always functions from the time power is applied to the board.

Certain EGMs use several power supply voltages to operate portions of the computer circuitry. These can be generated in a central power supply or locally on the computer board. If any of these voltages falls out of the tolerance limits of the circuitry they power, unpredictable operation of the EGM may result. Though most modern general purpose computing devices include voltage monitoring circuitry, these types of circuits only report voltage status to the operating software. Out of tolerance voltages can cause software malfunction, creating a potential uncontrolled condition in the general purpose computing device. Certain EGMs have power supplies with relatively tighter voltage margins than that required by the operating circuitry. In addition, the voltage monitoring circuitry implemented in certain EGMs typically has two thresholds of control. The first threshold generates a software event that can be detected by the operating software and an error condition then generated. This threshold is triggered when a power supply voltage falls out of the tolerance range of the power supply but is still within the operating range of the circuitry. The second threshold is set when a power supply voltage falls out of the operating tolerance of the circuitry. In this case, the circuitry generates a reset, halting operation of the EGM.

As described above, certain EGMs are state-based machines. Different functions of the game provided by the

EGM (e.g., bet, play, result, points in the graphical presentation, etc.) may be defined as a state. When the EGM moves a game from one state to another, the EGM stores critical data regarding the game software in a custom non-volatile memory subsystem. This ensures that the user's wager and credits are preserved and to minimize potential disputes in the event of a malfunction on the EGM. In general, the EGM does not advance from a first state to a second state until critical information that enables the first state to be reconstructed has been stored. This feature enables the EGM to recover operation to the current state of play in the event of a malfunction, loss of power, etc. that occurred just before the malfunction. In at least one embodiment, the EGM is configured to store such critical information using atomic transactions.

Generally, an atomic operation in computer science refers to a set of operations that can be combined so that they appear to the rest of the system to be a single operation with only two possible outcomes: success or failure. As related to data storage, an atomic transaction may be characterized as a series of database operations which either all occur, or all do not occur. A guarantee of atomicity prevents updates to the database occurring only partially, which can result in data corruption.

To ensure the success of atomic transactions relating to critical information to be stored in the EGM memory before a failure event (e.g., malfunction, loss of power, etc.), memory that includes one or more of the following criteria be used: direct memory access capability; data read/write capability which meets or exceeds minimum read/write access characteristics (such as at least 5.08 Mbytes/sec (Read) and/or at least 38.0 Mbytes/sec (Write)). Memory devices that meet or exceed the above criteria may be referred to as "fault-tolerant" memory devices.

Typically, battery-backed RAM devices may be configured to function as fault-tolerant devices according to the above criteria, whereas flash RAM and/or disk drive memory are typically not configurable to function as fault-tolerant devices according to the above criteria. Accordingly, battery-backed RAM devices are typically used to preserve EGM critical data, although other types of non-volatile memory devices may be employed. These memory devices are typically not used in typical general purpose computing devices.

Thus, in at least one embodiment, the EGM is configured to store critical information in fault-tolerant memory (e.g., battery-backed RAM devices) using atomic transactions. Further, in at least one embodiment, the fault-tolerant memory is able to successfully complete all desired atomic transactions (e.g., relating to the storage of EGM critical information) within a time period of 200 milliseconds or less. In at least one embodiment, the time period of 200 milliseconds represents a maximum amount of time for which sufficient power may be available to the various EGM components after a power outage event has occurred at the EGM.

As described previously, the EGM may not advance from a first state to a second state until critical information that enables the first state to be reconstructed has been atomically stored. After the state of the EGM is restored during the play of a game of chance, game play may resume, and the game may be completed in a manner that is no different than if the malfunction had not occurred. Thus, for example, when a malfunction occurs during a game of chance, the EGM may be restored to a state in the game of chance just before when the malfunction occurred. The restored state may include metering information and graphical information that was

displayed on the EGM in the state before the malfunction. For example, when the malfunction occurs during the play of a card game after the cards have been dealt, the EGM may be restored with the cards that were previously displayed as part of the card game. As another example, a bonus game may be triggered during the play of a game of chance in which a user is required to make a number of selections on a video display screen. When a malfunction has occurred after the user has made one or more selections, the EGM may be restored to a state that shows the graphical presentation just before the malfunction including an indication of selections that have already been made by the user. In general, the EGM may be restored to any state in a plurality of states that occur in the game of chance that occurs while the game of chance is played or to states that occur between the play of a game of chance.

Game history information regarding previous games played such as an amount wagered, the outcome of the game, and the like may also be stored in a non-volatile memory device. The information stored in the non-volatile memory may be detailed enough to reconstruct a portion of the graphical presentation that was previously presented on the EGM and the state of the EGM (e.g., credits) at the time the game of chance was played. The game history information may be utilized in the event of a dispute. For example, a user may decide that in a previous game of chance that they did not receive credit for an award that they believed they won. The game history information may be used to reconstruct the state of the EGM before, during, and/or after the disputed game to demonstrate whether the user was correct or not in the user's assertion.

Another feature of EGMs is that they often include unique interfaces, including serial interfaces, to connect to specific subsystems internal and external to the EGM. The serial devices may have electrical interface requirements that differ from the "standard" EIA serial interfaces provided by general purpose computing devices. These interfaces may include, for example, Fiber Optic Serial, optically coupled serial interfaces, current loop style serial interfaces, etc. In addition, to conserve serial interfaces internally in the EGM, serial devices may be connected in a shared, daisy-chain fashion in which multiple peripheral devices are connected to a single serial channel.

The serial interfaces may be used to transmit information using communication protocols that are unique to the gaming industry. For example, IGT's Netplex is a proprietary communication protocol used for serial communication between EGMs. As another example, SAS is a communication protocol used to transmit information, such as metering information, from an EGM to a remote device. Often SAS is used in conjunction with a player tracking system.

Certain EGMs may alternatively be treated as peripheral devices to a casino communication controller and connected in a shared daisy chain fashion to a single serial interface. In both cases, the peripheral devices are assigned device addresses. If so, the serial controller circuitry must implement a method to generate or detect unique device addresses. General purpose computing device serial ports are not able to do this.

Security monitoring circuits detect intrusion into an EGM by monitoring security switches attached to access doors in the EGM cabinet. Access violations result in suspension of game play and can trigger additional security operations to preserve the current state of game play. These circuits also function when power is off by use of a battery backup. In a power-off operation, these circuits continue to monitor the access doors of the EGM. When power is restored, the EGM

can determine whether any security violations occurred while power was off, e.g., via software for reading status registers. This can trigger event log entries and further data authentication operations by the EGM software.

5 Trusted memory devices and/or trusted memory sources are included in an EGM to ensure the authenticity of the software that may be stored on less secure memory subsystems, such as mass storage devices. Trusted memory devices and controlling circuitry are typically designed to not enable 10 modification of the code and data stored in the memory device while the memory device is installed in the EGM. The code and data stored in these devices may include authentication algorithms, random number generators, authentication keys, operating system kernels, etc. The purpose of these trusted memory devices is to provide gaming 15 regulatory authorities a root trusted authority within the computing environment of the EGM that can be tracked and verified as original. This may be accomplished via removal of the trusted memory device from the EGM computer and verification of the secure memory device contents is a separate third party verification device. Once the trusted 20 memory device is verified as authentic and based on the approval of the verification algorithms included in the trusted device, the EGM is enabled to verify the authenticity of additional code and data that may be located in the gaming computer assembly, such as code and data stored on hard disk drives.

In at least one embodiment, at least a portion of the trusted 30 memory devices/sources may correspond to memory that cannot easily be altered (e.g., "unalterable memory") such as EPROMS, PROMS, Bios, Extended Bios, and/or other memory sources that are able to be configured, verified, and/or authenticated (e.g., for authenticity) in a secure and controlled manner.

35 According to one embodiment, when a trusted information source is in communication with a remote device via a network, the remote device may employ a verification scheme to verify the identity of the trusted information source. For example, the trusted information source and the 40 remote device may exchange information using public and private encryption keys to verify each other's identities. In another embodiment, the remote device and the trusted information source may engage in methods using zero knowledge proofs to authenticate each of their respective 45 identities.

EGMs storing trusted information may utilize apparatuses or methods to detect and prevent tampering. For instance, trusted information stored in a trusted memory device may be encrypted to prevent its misuse. In addition, the trusted 50 memory device may be secured behind a locked door. Further, one or more sensors may be coupled to the memory device to detect tampering with the memory device and provide some record of the tampering. In yet another example, the memory device storing trusted information 55 might be designed to detect tampering attempts and clear or erase itself when an attempt at tampering has been detected.

Mass storage devices used in a general purpose computing devices typically enable code and data to be read from and written to the mass storage device. In a gaming environment, modification of the gaming code stored on a mass storage device is strictly controlled and would only be enabled under specific maintenance type events with electronic and physical enablers required. Though this level of security could be provided by software, EGMs that include 60 mass storage devices include hardware level mass storage data protection circuitry that operates at the circuit level to monitor attempts to modify data on the mass storage device 65

41

and will generate both software and hardware error triggers should a data modification be attempted without the proper electronic and physical enablers being present.

It should be appreciated that the terminology used herein is for the purpose of describing particular aspects only and is not intended to be limiting of the disclosure. For example, the singular forms "a", "an" and "the" are intended to include the plural forms as well, unless the context clearly indicates otherwise. In another example, the terms "including" and "comprising" and variations thereof, when used in this specification, specify the presence of stated features, steps, operations, elements, and/or components, but do not preclude the presence or addition of one or more other features, steps, operations, elements, components, and/or groups thereof. Additionally, a listing of items does not imply that any or all of the items are mutually exclusive nor does a listing of item simply that any or all of the items are collectively exhaustive of anything or in a particular order, unless expressly specified otherwise. Moreover, as used herein, the term "and/or" includes any and all combinations of one or more of the associated listed items. It should be further appreciated that headings of sections provided in this document and the title are for convenience only and are not to be taken as limiting the disclosure in any way. Furthermore, unless expressly specified otherwise, devices that are in communication with each other need not be in continuous communication with each other and may communicate directly or indirectly through one or more intermediaries.

Various changes and modifications to the present embodiments described herein will be apparent to those skilled in the art. For example, a description of an embodiment with several components in communication with each other does not imply that all such components are required, or that each of the disclosed components must communicate with every other component. On the contrary a variety of optional components are described to illustrate the wide variety of possible embodiments of the present disclosure. As such, these changes and modifications can be made without departing from the spirit and scope of the present subject matter and without diminishing its intended technical scope. It is therefore intended that such changes and modifications be covered by the appended claims.

The invention claimed is:

1. A electronic gaming system comprising:

a housing comprising an access door;

a security monitoring circuit supported by the housing, that monitors the access door, and that causes a signal to be sent to a remote server when the access door is opened;

a power distribution component supported by the housing;

a plurality of output devices comprising: a display device supported by the housing, a player tracking display supported by the housing, a ticket printer supported by the housing, and a speaker supported by the housing; a sound card supported by the housing and operable with the speaker;

a plurality of input devices comprising: a touch screen input device supported by the housing and operable with the display device, an acceptor supported by the housing, a validator supported by the housing, a player tracking card reader supported by the housing, and a cash-out button supported by the housing;

a processor supported by the housing; and

a trusted memory device supported by the housing and configured to provide a gaming regulatory authority a

42

root trusted authority that can be tracked and verified as original, the trusted memory device storing instructions that, when executed by the processor, cause the processor to cause a display, via the display device, of a credit balance after the acceptor receives a physical currency or a physical ticket, after the validator validates the physical currency or the physical ticket, and after the player tracking card reader reads a player identification from a player tracking device;

wherein the plurality of instructions, when executed by the processor, for a play of a game, cause the processor to:

determine a first display state of the electronic gaming machine by causing: a display, by a display device, of symbols at symbol display positions, the displayed symbols randomly selected from different symbols, the displayed symbols comprising a multi-evaluation trigger symbol, wherein the display of the multi-evaluation trigger symbol comprises a display of different alternative symbols of the multi-evaluation trigger symbol and an indication of a first one of the alternative symbols, wherein the different alternative symbols are each rotatable to a position that indicates application of that different alternative symbol, and

a display, by the display device, of an indication of any winning symbol combination formed by the displayed symbols and based on a first symbol evaluation comprising the first one of the alternative symbols of the multi-evaluation trigger symbol; when an opening of the access door is detected via the security monitoring circuit following the determination of the display state of the electronic gaming machine:

disable any occurrence of an alternative symbol rotation event,

store data associated with the display state of the electronic gaming machine, the stored data comprising rotational positions of the alternative symbols, and

following at least a closing of the access door detected via the security monitoring circuit:

load the stored data to reconstitute the display state of the electronic gaming machine, and enable an occurrence of the alternative symbol rotation event;

determine a second display state of the electronic gaming machine by causing: a display, by the display device, of an indication of a second one of the alternative symbols of the multi-evaluation trigger symbol, and

a display, by the display device, of an indication of any winning symbol combination formed by the displayed symbols and based on a second symbol evaluation comprising the second one of the alternative symbols of the multi-evaluation trigger symbol; and

determine a third display state of the electronic gaming machine by causing: a display, by the display device, of an indication of a third one of the alternative symbols of the multi-evaluation trigger symbol, and a display, by the display device, of an indication of any winning symbol combination formed by the displayed symbols and based on a third evaluation comprising the third one of the alternative symbols of the multi-evaluation trigger symbol.

2. The electronic gaming system of claim 1, wherein the plurality of instructions, when executed by the processor, cause the processor to determine a fourth display state of the electronic gaming machine by causing: a display, by the display device, of a first rotation of the different alternative symbols of the multi-evaluation trigger symbol associated with the display of the indication of the second one of the alternative symbols of the multi-evaluation trigger symbol.

3. The electronic gaming system of claim 2, wherein the plurality of instructions, when executed by the processor, cause the processor to determine a fifth display state of the electronic gaming machine by causing: a display, by the display device, of the first rotation of the different alternative symbols of the multi-evaluation trigger symbol based on a predetermined direction of rotation.

4. The electronic gaming system of claim 2, wherein the plurality of instructions, when executed by the processor, cause the processor to determine a fifth display state of the electronic gaming machine by causing: a display, by the display device, of a second rotation of the different alternative symbols of the multi-evaluation trigger symbol associated with the display of the indication of the third one of the alternative symbols of the multi-evaluation trigger symbol.

5. The electronic gaming system of claim 4, wherein a quantity of the rotations of the different alternative symbols of the multi-evaluation trigger symbol is less than a quantity of the different alternative symbols of the multi-evaluation trigger symbol.

6. The electronic gaming system of claim 4, wherein a quantity of the rotations of the different alternative symbols of the multi-evaluation trigger symbol is more than a quantity of the different alternative symbols of the multi-evaluation trigger symbol.

7. The electronic gaming system of claim 4, wherein the plurality of instructions, when executed by the processor, cause the processor to determine a sixth display state of the electronic gaming machine by causing: cause a display, by the display device, of an indication of a quantity of rotations of the multi-evaluation trigger symbol.

8. A electronic gaming system comprising:

a housing comprising an access door; a security monitoring circuit supported by the housing, that monitors the access door, and that causes a signal to be sent to a remote server when the access door is opened;

a power distribution component supported by the housing;

a plurality of output devices comprising: a display device supported by the housing, a player tracking display supported by the housing, a ticket printer supported by the housing, and a speaker supported by the housing; a sound card supported by the housing and operable with the speaker;

a plurality of input devices comprising: a touch screen input device supported by the housing and operable with the display device, an acceptor supported by the housing, a validator supported by the housing, a player tracking card reader supported by the housing, and a cash-out button supported by the housing;

a processor supported by the housing; and

a trusted memory device supported by the housing and configured to provide a gaming regulatory authority a root trusted authority that can be tracked and verified as original, the trusted memory device storing instructions that, when executed by the processor, cause the processor to cause a display, via the display device, of a

credit balance after the acceptor receives a physical currency or a physical ticket, after the validator validates the physical currency or the physical ticket, and after the player tracking card reader reads a player identification from a player tracking device;

wherein the plurality of instructions, when executed by the processor, for a play of a game, cause the processor to:

determine a first display state of the electronic gaming machine by causing: a display, by a display device, of symbols at symbol display positions, the displayed symbols randomly selected from different symbols, the displayed symbols comprising a plurality of multi-evaluation trigger symbols, wherein the display of each of the multi-evaluation trigger symbols comprises a display of alternative symbols of that multi-evaluation trigger symbol and an indication of a first one of the alternative symbols of that multi-evaluation trigger symbol, wherein the alternative symbols are each rotatable to a position that indicates application of that alternative symbol, and a display, by the display device, of an indication of any winning symbol combinations formed by the displayed symbols and based on one or more symbol evaluations comprising the first one of the alternative symbols of each of the multi-evaluation trigger symbols;

when an opening of the access door is detected via the security monitoring circuit following the determination of the display state of the electronic gaming machine:

disable any occurrence of an alternative symbol rotation event,

store data associated with the display state of the electronic gaming machine, the stored data comprising rotational positions of the alternative symbols, and

following at least a closing of the access door detected via the security monitoring circuit:

load the stored data to reconstitute the display state of the electronic gaming machine, and enable an occurrence of the alternative symbol rotation event:

determine a second display state of the electronic gaming machine by causing: a display, by the display device, of indications of second ones of the alternative symbols of each of the multi-evaluation trigger symbols, and

a display, by the display device, of an indication of any winning symbol combinations formed by the displayed symbols and based on one or more symbol evaluations comprising the second ones of the alternative symbols of the multi-evaluation trigger symbols;

determine a third display state of the electronic gaming machine by causing: a display, by the display device, of indications of third ones of the alternative symbols of each of the multi-evaluation trigger symbols; and a display, by the display device, of an indication of any winning symbol combinations formed by the displayed symbols and based on one or more symbol evaluations comprising the third ones of the alternative symbols of the multi-evaluation trigger symbols.

9. The electronic gaming system of claim 8, wherein the plurality of instructions, when executed by the processor, cause the processor to determine a fourth display state of the electronic gaming machine by causing a display, by the

display device, of first rotations of the alternative symbols of each of the multi-evaluation trigger symbol associated with the displays of the indications of the second ones of the alternative symbols of the multi-evaluation trigger symbols.

10. The electronic gaming system of claim 9, wherein the plurality of instructions, when executed by the processor, cause the processor to determine a fifth display state of the electronic gaming machine by causing a display, by the display device, of second rotations of the alternative symbols of each of the multi-evaluation trigger symbol associated with the displays of the indications of the third ones of the alternative symbols of the multi-evaluation trigger symbols. 5

11. The electronic gaming system of claim 9, wherein the plurality of instructions, when executed by the processor, cause the processor to determine a fifth display state of the electronic gaming machine by causing a display, by the display device, of the first rotations of the alternative symbols of each of the multi-evaluation trigger symbols and the indication of the second ones of the alternative symbols of each of the multi-evaluation trigger symbols based on predetermined directions of rotation. 15

12. The electronic gaming system of claim 11, wherein the predetermined directions of rotation are a same direction of rotation. 20

13. The electronic gaming system of claim 8, wherein the each of the multi-evaluation trigger symbols only comprises the first one, the second one, and the third one of the alternative symbols. 25

14. The electronic gaming system of claim 8, wherein at least two of the multi-evaluation trigger symbols comprise different alternative symbols. 30

15. The electronic gaming system of claim 8, wherein each of the multi-evaluation trigger symbols comprise the same alternative symbols. 35

16. A electronic gaming system comprising:
a housing comprising an access door;
a security monitoring circuit supported by the housing, that monitors the access door, and that causes a signal to be sent to a remote server when the access door is 40 opened;

a power distribution component supported by the housing;
a plurality of output devices comprising: a display device supported by the housing, a player tracking display 45 supported by the housing, a ticket printer supported by the housing, and a speaker supported by the housing;
a sound card supported by the housing and operable with the speaker;

a plurality of input devices comprising: a touch screen input device supported by the housing and operable with the display device, an acceptor supported by the housing, a validator supported by the housing, a player tracking card reader supported by the housing, and a cash-out button supported by the housing; 50

a processor supported by the housing; and

a trusted memory device supported by the housing and configured to provide a gaming regulatory authority a root trusted authority that can be tracked and verified as original, the trusted memory device storing instructions that, when executed by the processor, cause the processor to cause a display, via the display device, of a credit balance after the acceptor receives a physical currency or a physical ticket, after the validator validates the physical currency or the physical ticket, and 60 after the player tracking card reader reads a player identification from a player tracking device; 65

wherein the plurality of instructions, when executed by the processor, for a play of a game, cause the processor to:

determine a first display state of the electronic gaming machine by causing: a display, by a display device, of symbols at symbol display positions, the displayed symbols randomly selected from different symbols, the displayed symbols comprising a first multi-evaluation trigger symbol and a second first multi-evaluation trigger symbol, wherein the display of the first multi-evaluation trigger symbol comprises a display of alternative symbols of the first multi-evaluation trigger symbol and an indication of a first one of the alternative symbols of the first multi-evaluation trigger symbol, and wherein the display of the second multi-evaluation trigger symbol comprises a display of alternative symbols of the second multi-evaluation trigger symbol and an indication of a first one of the alternative symbols of the second multi-evaluation trigger symbol, wherein the alternative symbols are each rotatable to a position that indicates application of that alternative symbol, a display, by the display device, of an indication of any winning symbol combination formed by the displayed symbols and based on a first symbol evaluation comprising the first one of the alternative symbols of the first multi-evaluation trigger symbol, and

a display, by the display device, of an indication of any winning symbol combination formed by the displayed symbols and based on a second symbol evaluation comprising the first one of the alternative symbols of the second multi-evaluation trigger symbol;

when an opening of the access door is detected via the security monitoring circuit following the determination of the display state of the electronic gaming machine:

disable any occurrence of an alternative symbol rotation event,

store data associated with the display state of the electronic gaming machine, the stored data comprising rotational positions of the alternative symbols, and

following at least a closing of the access door detected via the security monitoring circuit:

load the stored data to reconstitute the display state of the electronic gaming machine, and enable an occurrence of the alternative symbol rotation event; and

determine a second display state of the electronic gaming machine by causing: a display, by the display device, of an indication of a second one of the alternative symbols of the first multi-evaluation trigger symbol,

a display, by the display device, of an indication of any winning symbol combination formed by the displayed symbols and based on a third symbol evaluation comprising the second one of the alternative symbols of the first multi-evaluation trigger symbol,

a display, by the display device, of an indication of a second one of the alternative symbols of the second multi-evaluation trigger symbol, and

a display, by the display device, of an indication of any winning symbol combination formed by the displayed symbols and based on a fourth symbol evalua-

47

ation comprising the second one of the alternative symbols of the second multi-evaluation trigger symbol.

17. The electronic gaming system of claim **16**, wherein the plurality of instructions, when executed by the processor, cause the processor to determine a third display state of the electronic gaming machine by causing: a display, by the display device, of a first rotation of the alternative symbols of the first multi-evaluation trigger symbol and a first rotation of the alternative symbols of the second multi-evaluation trigger symbol. ¹⁰

18. The electronic gaming system of claim **17**, wherein the plurality of instructions, when executed by the processor, cause the processor to determine a fourth display state of the electronic gaming machine by causing: a display, by the display device, of first rotations of the alternative symbols of the first and second multi-evaluation trigger symbols based on predetermined directions of rotation. ¹⁵

19. The electronic gaming system of claim **18**, wherein the predetermined directions of rotation are a same direction of rotation. ²⁰

48

20. The electronic gaming system of claim **16**, wherein the plurality of instructions, when executed by the processor, cause the processor to determine a further display state of the electronic gaming machine by causing:

a display, by the display device, of an indication of a third one of the alternative symbols of the first multi-evaluation trigger symbol;

a display, by the display device, of an indication of any winning symbol combination formed by the displayed symbols and based on a fifth symbol evaluation comprising the third one of the alternative symbols of the first multi-evaluation trigger symbol;

a display, by the display device, of an indication of a third one of the alternative symbols of the second multi-evaluation trigger symbol; and

a display, by the display device, of an indication of any winning symbol combination formed by the displayed symbols and based on a sixth symbol evaluation comprising the third one of the alternative symbols of the second multi-evaluation trigger symbol.
